RECORD CARD SYSTEM

Cleon E. Shields, New York, and Herbert S. Gardner, Scarsdale, N. Y., and John F. Milligan, Ridgefield Park, N. J., assignors, by direct and mesne assignments, to Rapidata Corporation, New York, N. Y., a corporation of Delaware

Application September 13, 1940, Serial No. 356,616

113 Claims. (Cl. 164—112)

This invention relates to record card systems and more particularly to record card systems in which the individual cards are provided with a plurality of columns of index point positions, in which pertinent information data are recorded by punching holes in the individual columns so as to make it possible to analyze the recorded data by segregating the cards having the desired information from the other cards.

Among the objects of the invention is a card system of the foregoing type utilizing an improved form of card arrangement which makes it possible to segregate the cards containing the desired information without resort to special expensive segregating or tabulating machines; a novel card punching arrangement for automatically punching the pertinent information on such cards; and an improved arrangement for correlating such cards with the punching arrangement to assure that the card punching is carried on in an efficient and foolproof manner.

The foregoing and other objects of the invention and the various features thereof will be best understood from the following description of exemplifications thereof, reference being had to the accompanying drawings wherein

Fig. 1 shows the face of one form of a record card blank for a card recording system of the invention;

Fig. 2 is a view similar to Fig. 1 illustrating the card blank of Fig. 1 with the information recorded thereon;

Fig. 3 is a view similar to Fig. 1 illustrating an array of disarranged superposed record cards which have to be sorted;

Figs. 4A and 4B are parts of a diagrammatic view illustrating the cooperative relationship of one form of a record punching mechanism and the associated electric circuit exemplifying the invention;

Fig. 5 is a plan view of a machine embodying the mechanisms of Figs. 4A and 4B;

Fig. 6 is a cross-sectional view along line 6—6 of Fig. 5;

Fig. 7 is a cross-sectional view along line 7—7 of Fig. 5;

Fig. 8 is an elevational view of the punch carrier of Figs. 5 to 7;

Fig. 9 is an elevational view along line 9—9 of Fig. 5 illustrating the punch driving coupling clutch and the associated operating elements of the machine;

Fig. 10 is a view similar to Fig. 9 of the carrier advancing coupling clutch and the associated operating elements of the machine;

Fig. 11 is a view along line 11—11 of Fig. 5; Fig. 12 is a view along line 12—12 of Fig. 5; and

Fig. 1A shows another form of record card blank.

The card system of the invention utilizes card blanks 20, one particular form of which is shown in Fig. 1. The card blanks are made of a suitable paper stock, and have a recorded area provided with series of index columns, indicated, for instance, by the letters A to L, corresponding to the different index positions of the card. The pertinent information is recorded in each column by punching it so as to leave in the column only a single bridge, indicated, for instance, by digits 0 to 12, corresponding to the different items of information that are to be recorded in a given column in accordance with a predetermined code, in the way shown in Fig. 2 in which each index position column has left only one bridge made at a predetermined position according to the recorded data.

The card blank 20 is also provided with additional areas on which pertinent data may be recorded, by a typewriter, for instance. In the card recording and punching system of the invention, the card blanks on which the pertinent data are to be recorded, such as blank 20, of Fig. 1, have already formed in each column a series of holes which separate the different bridges corresponding to the different items of information that have to be recorded, in the given column, so that for recording the desired information in a given index position column, it is merely necessary to remove by punching all bridges except the bridge corresponding to the information, in the way shown, for instance, in Fig. 2, having recorded thereon a code 12—4—3—2—4—1—3—2—1—7—8—6.

Each card blank 20, such as shown in Fig. 1, on which the information is to be recorded, has a cutoff corner 21, for instance, in the upper right-hand corner, to fix the position of the card in which it has its right side up, and facing out. In addition, it has in the corner diagonally opposite to the cutoff corner 21 an elongated lifting slot 22 which, in combination with two lifting holes 23, 24 in the two other diagonally opposite corners of the card, make it easy to sort a disarranged stack of such cards to bring them all to the right-side-up, facing-out position, by using a needle on one vertical side of the card stack only. The elongated lifting slot 22 extends inwardly a distance slightly larger than the distance between the center of two adjacent bridges, so as to enable restoring of an irregularly mixed

up stack of cards to their properly aligned condition. Thus, if, as shown in Fig. 3, a disarranged stack or pile of cards has, in addition to a group of cards 20 with the cutoff 21 on the right upper corner, three other groups of cards 20—X, 20—Y, 20—Z with the cutoffs in the other three corners, the cards may be readily arranged in their proper order by proceeding as follows: Insert a sorting needle in the hole exposed above the cutoff right upper corner, and lift the cards on the needle, leaving the orderly arranged group of cards 20 having the cutoff corner in the right upper end. The needle is then inserted in the right lower hole of the pile of lifted cards and the cards picked up by the needle are withdrawn to the right, leaving in order another group of all cards 20—X.

The needle, which still engages the right lower hole of the withdrawn cards, is then lifted along the corner slot 22 of the cards 20—Z of the card pile, thereby raising the right upper corner of the cards 20—Y, thus separating them from the remaining cards 20—Z, whereupon all four groups of cards may be placed in their proper, right-side-up, facing-out position. An additional hole 25 is also provided near the cutoff corner 21.

The cutoff corner and the lifting holes 23 to 25 are located in the same position in each card. The outer edge of the lifting holes 22 to 25 are spaced from the adjacent edge of the card by a distance of the order of the distance between the centers of the two index bridges of the card so that when a card is lifted by one step, corresponding to one bridge, the lifting hole of the desired card projects above the level of the edges of the other cards in the stack so as to permit insertion of a needle into the projecting lifting hole and removal of the desired cards from the other cards of the stack.

By removing from each index position column all bridges except the bridge corresponding to the given information recorded therein, it is possible to segregate from a pile of cards all cards having the desired information by a simple lifting operation.

In order to segregate from a pile of such recorded cards, of the general form shown in Fig. 2, all cards of a given code, for instance, with the code B—4, it is merely necessary to insert a needle or rod through the opening under the bridge space M—4 of the upper card so as to pass through all cards of the pile, and lift the needle, which automatically engages all cards having bridges B—4 and lifts them at least by one bridge spacing above all other cards of the pile, whereupon the lifted cards, which are thus positively segregated from the other cards, may be withdrawn from the card pile by merely inserting a needle in one of the upper lifting holes 23, 25 of the so-segregated cards, and removing them for performing the desired analysis.

The segregation operation is instantaneously and automatically checked by a glance on the pile of segregated cards, because in all cards the elongated holes above and below the desired bridge B—4, for instance, are aligned, and must present an unobstructed light passage. A record system of the type described above makes thus possible positive and accurate segregation of the desired cards from the unwanted cards with which they are intermingled, without requiring intermediate segregation steps, and without the possibility of including unwanted cards among the cards with the desired information.

Such record card system makes it also easy to

5 segregate from a stack of record cards all cards having a specific type of information recorded in different bridges or rungs of an index column. Thus, for instance, if it is desired to segregate all cards having information recorded in the first five divisions of a single digit code represented by the five bridges 0 to 4 of column C, it is merely necessary to insert the segregating needle into the pile of cards through the opening under bridge space 4 of column C of the card stack, as indicated on the face of the front card, and lift the needle, which automatically engages and lifts all cards having bridges at 4 or higher, whereupon the cards which remain at the lower level are withdrawn by inserting another needle in one of their lower lifting holes 22, 24 and withdrawing them to the right or the left.

In order to properly record the information in each index column of a card blank, of the type shown in Fig. 1, by punching therein slots which leave only one bridge in an index column position, there is provided a key actuated punching mechanism which automatically aligns the individual index rows of the card with the stamp punches of a punch carrier, and automatically punches in the card the desired information.

One form of such card punching mechanism is illustrated diagrammatically in Figs. 4A and 4B and structurally in Figs. 5 to 12. The entire mechanism is assembled and held in its operative relationship on a bed frame 30 which in the form shown has a generally U-shaped wall structure and is made of cast-iron, for instance. In the flanged upper portion of its rear wall is formed a guide channel 31 in which is slidably guided an elongated card carrier 32 made in the form of a bar having a flat exposed surface and two upwardly projecting short register pins 33 on which the upper holes 23, 25 of a card blank 20, such as shown in Fig. 1, are placed, so that by moving the card carrier 32 along its guide channel 31, the card 20 is advanced along the upper surface of the bed frame 30 which is covered by table plates 34 which are aligned with the exposed surface of the card carrier 32 and suitably secured thereto, as by screws.

Means are also provided for automatically aligning the card carrier 32 in successive predetermined punching positions, as it is moved along its guide channel path 31. To this end, the rear edge of the carrier bar is provided with tapered aligning slots 36 and the underlying rear portion of the guide channel body is cut away so that aligning slots 36 of the carrier bar 32 project beyond the underlying edge of the bed frame wall. One of the aligning slots 36 is engaged by the curved end surface of a register lever 37 pivotally mounted on a shaft 38 held on a suitable bracket 39 secured to the rear wall of the bed 30 and biased by a spring 39', such as a compression spring, so as to hold the card carrier 32 in an aligned position and resist its displacement from an aligned position.

The aligning slots 36 and lever 37 with its biasing spring 39 are so arranged and designed that when the card carrier 32 is advanced by an external force along its guide channel 31, the aligning lever 37 snaps into and engages the next aligning slot 36 as soon as its edge reaches the aligning lever 37, thereby assuring that the card carrier 32 is automatically retained in successive predeterminedly aligned positions, as it is advanced along its guide channel 31. A retainer sheet 41, of spring metal, for instance, having its rear edge secured, as by screws, to the rear edge

of the bed frame, has a liplike front edge 42 overlying the border of the card so as to keep the card 20 registered with the pins 33 of the card carrier 32 while permitting easy insertion and removal of the card from the card carrier 32.

In the form shown, the retainer sheet 41 extends longitudinally along a portion of the guide channel and terminates at its left end in a right angularly bent spring finger projection 43 extending transversely above the underlying card 10 and holding it down on the underlying table surface. In addition, an elongated spring finger 44 having its left end secured, as by a screw, to a lateral bracket projection 45 suitably affixed to the rear wall of the bed frame 30, extends longitudinally over the other portion of the underlying bed table surface so as to retain the card in its aligned position on the card carrier 33 while it is advanced below the finger 44.

The punching mechanism for slotting the 20 aligned index rows of the record cards is mounted in the central portion of the bed frame 30. The desired slots in each index row of the card are punched by a set of rectangular punch bars 51 aligned in a row and suitably mounted in a punch carrier 50 for cooperation with an underlying die plate 52 which is aligned with the table surface and has a die slot 53 aligned below the row of punch bars 51. The die plate 52 is suitably mounted, as by screws, on a transverse channel member 54 of the bed frame 30 having a slot 55 through which paper waste drops down into a tray 56 slidably positioned between the side walls of the frame 30.

The punch carrier 50 has a flat guide surface bordered by two shoulders 61 and a facing wall member 62 having its ends suitably affixed, as by screws, to the shoulders 61, so as to form a transversely extending flat guide channel 63 within which the punch bars 51 are held aligned in a row above the underlying die slot 53. There are as many punch bars 51 as there are bridges in each index column of the card, so that when all punch bars are used to perform a punching operation, a slit is formed through the entire height of an index column.

The punch carrier also has mounted in the ends of its punch bar channel 63 two aligning bars 64 at the opposite ends of the row of punch bars 51. The aligning bars 64 are fixed in their positions in the punch carrier 50 and their outward ends 64' project slightly beyond the lowermost position of the punch bars 51 and serve to engage the upper and lower aligning slots 26 formed in the card blank 20 so as to assure that each time a punching operation is performed on a record card 20, the index row of the card which is to be punched is properly aligned with the row of punch bars 51.

As seen from Figs. 4 to 8, the lower ends of the aligning bars are rounded so that on entering the aligning slots 26 of a record card 20, which was, for instance, slightly misaligned during the preceding advancing step, they automatically restore the card to a position of alignment with the row of punch bars 51 and thus assure proper alignment of the index row with the punch bars during the punching operation. In addition, the lower outer ends of the aligning bars 64 are slightly tapered and have a slightly shorter cross-sectional area than the aligning slot of the card to facilitate the aligning operation. It should be noted that the aligning bars 64 do not extend to the inward edge of the aligning slots 26 of the record card 20 because the bridge extending 75

from the inward edge of the aligning slots of the cards lies under the punch bars 51 adjoining the aligning bars 64.

Means are also provided for raising a predetermined selected punch bar to a higher level than the other punch bars that are aligned with it in the punch carrier channel 63 so that on performing a punching operation on an underlying card, the bridge underlying the raised punch bar is left intact and not cut out.

By combining record cards in which the coded data are recorded in the different positions of each index row formed of bridges separated by holes by leaving therein only one bridge, with a 15 punching mechanism utilizing abutting punches held aligned in a row above the individual bridges of the cards, and registering therein the desired data by longitudinally displacing a selected punch bar relatively to the other punch bars, so that in the punching operation only the bridges underlying the other punches have to be removed, a very simple punch mechanism is able to make very accurate records in a very compact index position column occupying a very little card area.

Various arrangements may be used for setting the punches by selectively raising a predetermined punch bar depending on the information which is to be recorded in a given index column.

In the form of arrangement shown in Figs. 4 to 8, each punch bar 51 is provided with a transverse cam follower cutout 71 along one of its edge portions arranged to engage a cam bar 72, extending transverse to the plane of the punch bars and longitudinally guided by a row of slots 13 formed in the facing wall member 62 of the punch guide channel 63, and a similar row of slots 74 formed in a bar 75 secured at its ends, as by screws, to the opposite surface of the punch carrier plate 50.

Each cam bar 72 has cam surface portions 76, 77 shaped so that when the cam bar 72 is pushed inwardly from the full line position shown in Fig. 7 to the dotted line position 72', the raised portion of the upper cam surface 76 lifts the punch bar 51 to a level sufficiently higher than the level of the other punch bars 51 so that when a card punch operation is performed, the bridge underlying the raised punch bar 51 is left intact in the card and only all other bridges in the underlying index row are punched out.

When the cam bar 72 is returned from its dotted line position 72' to its full line position, its lower cam surface 77 acts on the lower edge of the punch bar cutout 71 to return it to its normal lower position shown in Fig. 7. As will be seen from Fig. 7, the down and upward motion of the punch carrier 50 imparts the up and down motion to the punch bars 51 not directly, but indirectly, through the engagement of its slotted portions 13, 75 with the cam bars 72, each cam bar 72 transmitting the punching forces to the punch bars engaged thereby.

Any of the known types of key actuated mechanically, electrically or electromechanically operated arrangements used in similar appliances may be utilized for selectively controlling a card punching mechanism of the type described above so that upon actuation of a selected key, one selected punch bar 51 is raised to a higher level than the other punch bars aligned with it above the underlying index position column of the record card for performing thereon the desired punching operation. Any desired number of similarly arranged and operated rows of punch bars

51 may be combined in a punch carrier for punching the desired information data in the index rows aligned under the individual rows of punches.

In the form of arrangement shown in Figs. 5 to 8, only one row of punch bars 51 is mounted in the punch carrier, and each index row of the card is advanced before performing thereon the desired punching operation.

The punch carrier 50 is suitably guided in its up and down motion within a guide channel 81 of a guide structure 82, extending in the form of a cantilever beam from a mounting post 80 suitably secured, as by screws, to a block 83 extending from the rear wall of the bed frame 30.

The punch carrier 50 is held in its position within the guide channel 81 by two flange members 84 suitably secured, as by screws, to shoulder portions of the guide structure extending vertically along the borders of the punch carrier, the lower ends of the flange member 84 having secured thereto, as by screws, two cross bars 85, extending above the die slot 53 of the die plate 52 and forming a guide passage for the lower ends of the aligned punch bars 51, directly above the underlying card and the die slot 53.

One form of a key actuated electromechanical control arrangement for such punching mechanism is shown in Figs. 4 to 11 of the drawings. Motive power for automatically performing the punching operation is supplied by an electric motor 85 which, together with a suitable reduction gear mechanism including a worm gear drive 86, is suitably held, as by screws, on a suitable mounting surface of the supporting post 80 extending from the frame bed 30. The motor-driven worm gear drive 86 rotates a drive shaft 87 suitably journaled in bearings formed in the body of the post 80 and a bearing bracket 88 (Figs. 6 and 11) suitably held as by screws to the rear surface of the bed frame 30. The rotary motion of the shaft 87 is utilized to selectively impart the up and down motion to the punch carrier 50 by a suitable selectively operated coupling mechanism 90.

In the form shown in Figs. 4 to 6 and 9, the coupling mechanism 90 for selectively operating the punch carrier 50 is formed of a ratchet coupling comprising a ratchet wheel 91 affixed as by a pin to the driving shaft 87 and a coupling drum 93 formed at one end of an eccentric member 94 revolvably mounted on the driving shaft 87, and driving through an eccentric rod 95 a lever 96 pivoted on a stud 97 held by the supporting post 80 projecting from the bed frame 30 and having its other end pivotally connected to an ear 98 of the punch carrier 65 for imparting thereto one down and up punching motion cycle during one revolution of the eccentric 94.

Selective coupling of the drive shaft 87 and the coupling drum 93 which drives the punch carrier 50 is established by a coupling pawl 101 which is pivotally mounted on a stud 102 extending from the inner wall of the coupling drum 93 and is pressed by a biasing spring 103 into coupling engagement with a tooth of the ratchet wheel 91 and rotated thereby if the other hook-shaped end 104 of the coupling pawl 101 is released from its engagement, through a window 93' in the coupling drum 93, with a cam projection 105' of a coupling lever 105 suitably pivoted on the shaft 38 mounted on the bracket 39 secured to the rear wall of the bed frame 30, the lever 105 being biased to the uncoupling

position shown in Figs. 4A and 9 by a biasing spring 108 extending from a control lever 109 that is affixed, as by a pin, to a control shaft 110 which is pivotally mounted on a bearing in the beam post 80 and another bearing bracket suitably supported on the left rear edge portion of the bed frame 30.

The control arm 109 is biased by a spring 112 extending from a higher portion of the post 80 (Fig. 11) so as to normally hold the control arm 109 in the position shown in Figs. 4A and 9 in which it keeps through the biasing spring 108 the coupling lever 105 in its inward uncoupling position in which it holds the coupling pawl 101 out of engagement with the coupling ratchet 91 and maintains the driving shaft 87 normally uncoupled from the punch-carrier driving coupling drum 93.

The control arm 109 of the punch carrier coupling 90 carries on a pivot stud 114 a cam arm 115 having a projecting cam surface 116 arranged to engage a follower pin 117 extending from the coupling lever 105, the cam arm 115 being held biased by a spring 118 against a stop pin 119 so as to keep its cam surface projection 116 out of engagement with the follower pin 117 of the coupling lever 105 as long as the control lever 109 is in its normal neutral position shown in Figs. 4A and 9.

The several elements of the coupling 90 and the associated control arm 109 are so arranged and proportioned that when the control arm 109 is tilted against the tension of its return spring 112, the cam surface portion 115' of the cam lever 115 engages the cam follower pin 117 of the coupling lever 105 and tilts it to the outward position until it releases the coupling pawl hook 104 and causes the coupling pawl 101 to instantaneously engage the coupling ratchet 91 and establish a driving connection between the driving shaft 87 and the punch carrier actuating eccentric 94, for performing a punching operation while the driving shaft 87 makes one rotation.

The coupling drum 93 carries on the wall 121 facing the control arm 109 a cam follower pin 122 so arranged that as soon as the coupling drum 93 starts to rotate, the pin 122 engages the inner surface 115' of the control lever cam arm 115 and tilts it around its pivot 114 until its outwardly tilted cam surface projection 116 moves past the cam follower pin 117 of the coupling lever 105, whereupon its biasing spring 108 tilts the coupling lever 105 inwardly to the position in which its hooked portion 105' engages and rides on the periphery of the rotating coupling drum 93, thereby assuring that at the end of one rotation, the hook portion 105' of the coupling lever 105 again engages the hooked end 104 of the coupling pawl 101 and forces it back to the uncoupling position shown in Figs. 4A and 9, thereby automatically breaking the driving connection from the shaft 87 to the punch carrier 50 at the end of one revolution of the coupling drum 93.

In other words, the coupling mechanism between the driving shaft 87 and the punch carrier 50 with its control arrangement are so designed and proportioned that when the control arm 109 is actuated to establish the coupling connection between the driving shaft 87 and the punch driving mechanism, the motion imparted to the coupling mechanism automatically sets into operation means for breaking the coupling

connection at the end of a single punching cycle.

Means are also provided to assure that at the end of a punching cycle the card carrier is automatically advanced to its next position.

In the form of the invention shown in Figs. 4A, 4B, 5, 9 and 11, there is mounted, to this end, on the driving shaft 81 a coupling unit 130, similar to the ratchet coupling 90 of the punch carrier drive, except that the periphery of its coupling drum is provided with a single helical tooth 131 arranged to engage a tooth 132 of a rack 133 secured to the adjacent edge of the card carrier 32, so that one rotation of the coupling mechanism 130 advances the card carrier 32 to its next alignment position. The teeth 132 of the card advancing rack 133 have the same pitch as the teeth between the alignment slots 36 of the card carrier. The starting end 134 and the finishing end 135 of the helical tooth 131 are separated by a gap which normally lies opposite the tooth 132 of the carrier rack 133 making it possible for the card carrier 32 to be moved longitudinally in its guide channel 31 without interference with the helical driving tooth 131 of the coupling unit 130. The edge of the starting end 134 of the card advancing helical tooth 131 is rounded so as to facilitate its entrance between, and automatic alignment with, the teeth of the advancing rack 133, and its finishing end 135 is beveled so as to release its engagement with the coupling rack 122 at the end of its revolution in a proper position, in which the action of the aligning lever 37 engages one of its aligning slots 36 and brings it into a position of alignment relatively to the punch bars 51.

The coupling lever 105 of the carrier advancing coupling 130 which has all the elements of the punch carrier coupling 90, is normally maintained in its uncoupling position shown in Figs. 4A, 4B, 9 and 10 by a follower pin 135 projecting therefrom and engaging a cam slot 136 of a control arm 137 pivotally mounted on the control shaft 110 and biased to the position shown by a spring 112 extending from a cross bar 138 held above it by the wall of the punch carrier guide structure 82 and an extension 139 of the bearing bracket 111 of the drive shaft 81.

An additional biasing spring 141 extends from the control arm 137 to the coupling lever 105 holding its follower pin 135 in engagement with the cam slot 136 when the control arm 137 is tilted. The several elements associated with the carrier advancing coupling 130 are so arranged and proportioned that when its control arm 137 is tilted upwardly, its cam 136 actuates through the follower pin 135 the coupling lever 105 to the uncoupling position, thereby establishing the coupling connection between the shaft 81 and the coupling drum 93 of the card advancing coupling 130, so as to advance by a rotation of its helical tooth 131 the card carrier 32 one step to the next index position column.

In the form of the invention shown in Figs. 4A, 4B, 5, 9, 10 and 11, the operation of the punch driving coupling 90 is utilized to start at the end of the punching cycle a card advancing cycle.

In the arrangement shown, automatic actuation of the carrier advancing coupling 130, immediately after completion of a punching operation, is effected by providing the control arm 137 of the carrier advancing coupling 130 with a cam projection 143 having an inwardly facing cam surface which is arranged and shaped to be engaged by the cam follower pin 122 of the

5 punch carrier coupling 90 shortly before the end of one revolution cycle, after completion of the punching operation, so as to tilt the control arm 137 of the card advancing coupling 130 to the uncoupling position in which its coupling lever 105 is tilted to couple the driving shaft 81 to the carrier advancing coupling drum tooth 131 and advances the card carrier to the next punching position. Since the control arm 137 of the carrier advancing coupling 130 has been released from its engagement with the follower pin 122 of the punch carrier coupling 90, at the end of its revolution, the coupling lever 105 of the carrier advancing coupling 130 is likewise released, and its hook 105' rides now on the periphery of its rotating coupling drum 93 until at the end of one revolution, the hook 105' again engages the hooked end 141 of the coupling pawl 101 and automatically uncouples the carrier advancing coupling 130 from the driving shaft 81, thereby terminating the card advancing cycle.

There are also provided means for automatically assuring that the punching mechanism is prevented from being operated if the card carrier 32 is not properly aligned relatively to the punch carrier, with an index column of the record card 20 properly aligned under the row of punching bars 51.

As shown diagrammatically in Figs. 4A and 30 4B, such automatic protection is secured by a special control arrangement for the motor 85 which is used to operate the punching mechanism and advance the carrier. The motor 85 which is supplied from a conventional domestic A. C. 25 or D. C. 110 volt circuit, indicated by a plug 145, is energized through a circuit which is arranged to be completed either by the closure of a normally open punch actuating switch 146 and a serially connected lockout switch 147, for performing a punching operation, or by the closure of either one of the switches 148, 149, for performing a card advancing or card back spacing operation, respectively.

As shown in Figs. 4B and 10, the lockout switch 147 is arranged to be operated by an arm of the aligning lever 37 which, as explained above, is biased to retain engagement with an aligning slot 36 of the card carrier bar 32 and hold it in a predetermined aligned position relatively to the punch carrier. As long as the aligning slot 36 of the card carrier 32 retains its engagement with the pin of the aligning lever 37, the lockout switch 147 remains closed and prepares a circuit through which the driving motor 85 may be energized to drive the punching mechanism when the punch actuating switch 146 is closed.

However, if in advancing the card carrier bar 32 from one aligned position to the next, it is left in an intermediate misaligned position in which the pin of the register lever 37 is kept out of engagement with an aligning slot, the lever 37 opens the lockout switch 147 and thereby prevents energization of the driving motor 85 as long as the card carrier 32 remains in a misaligned position.

The above described arrangement of the aligning lever 37 for aligning the punch carrier in its successive steps as it is being advanced, in combination with a lockout switch which is actuated by the aligning lever to open the motor energizing circuit and prevent a punching operation while the aligning lever is out of engagement with an aligning slot of the card carrier as it is advanced from one aligned position to the next

automatically serves thus as means for preventing a punching operation while the carrier is being advanced to the next punching step.

As shown in Figs. 4A, 4B, 10 and 11, the card advancing coupling 130 is also provided with a cam disc 155 which is suitably secured thereto, as by screws, and has a circular peripheral cam surface provided with a depression 156 engaging a cam follower projection 157 of an arm extending from the aligning lever 131 so that when the card advancing coupling 130 is in its normal uncoupled position shown, the lockout switch 147 remains closed, and that as soon as the carrier advancing coupling is started to rotate, to advance the card carrier 32, the raised peripheral surface of the cam disc 155 actuates the cam follower 157 to its downward position so as to operate the lockout switch 147 and prevent energization of the motor through the punch actuating switch 148 until, at the end of one revolution of the card advancing coupling 130, the cam follower 157 is released to the cam depression 156 of the cam 155 and the lockout switch 147 is again opened.

The card advancing switch 148 is associated with the card advancing coupling 130 and is arranged to be automatically closed when the coupling connection between the shaft 87 and the carrier advancing coupling tape 130 is established. In the form shown, the normally open carrier advancing switch 148 is so arranged that when the control arm 137 of the carrier advancing coupling 130 is tilted to actuate the associated coupling lever 105 to the coupling position and establish the coupling connection for advancing the card carrier to the next step, the coupling lever 105 automatically actuates the card advancing switch 148 to the closed position in which it energizes the motor 85 to drive the shaft 87 and perform the card advancing operation, the switch remaining closed while the cam projection 105 of the coupling lever rides along the outer periphery of the coupling drum of the carrier advancing coupling 130 till at the end of one revolution, after the card carrier has been advanced to its next step, the coupling lever 105 is released to its inward uncoupling position and the switch 148 again opens the motor circuit.

As shown in Figs. 4A, 4B, 5 and 10, the carrier advancing rack 133 is not a rigid part of the card carrier bar 32, but is yieldably mounted thereon so as to prevent jamming of its teeth with the tooth 131 of the carrier advancing coupling drum if the latter is set in operation while the card carrier bar 32 is in a misaligned position.

In the form shown, the advancing rack 133 is hingedly mounted on two hinges 151 which are secured to the card carrier bar 32, a biasing spring 152 being provided to hold the rack 133, which is made of a flat sheet metal piece, against the underlying edge portion of the carrier bar 32, and permit it to yield and be tilted upwardly to the dotted line position 133', shown in Fig. 10, if the card advancing tooth 131 of the card advancing coupling 130 is set to rotate while the card carrier 32 is in a misaligned position.

This arrangement also assures that when the coupling connection to the carrier advancing coupling is actuated to advance the carrier while the card carrier 32 is in a misaligned position, the rotary motion imparted to the helical card advancing tooth 131 of the coupling 130 will automatically engage the adjacent slot in the upwardly tilted carrier advancing rack 133, when its periphery reaches the next tooth slot, whereupon the 70

rack is returned by its biasing spring 152 to its normal downward position and the further motion of the tooth 131 of the carrier advancing coupling 130 moves the card carrier 32 forward to its next alignment position.

The card carrier 32 may also be advanced from one position to another position without operating the punching mechanism by simple direct actuation of the control arm 137 of the card advancing coupling 130.

The card-carrier back-spacing switch 149 is also shown associated with a coupling 130-B, similar in every respect to the carrier advancing coupling 130, except that its helical tooth 131-B has an oppositely directed pitch so that during a revolving motion of the coupling 130-B, its helical tooth 131-B engages a tooth 132 of the carrier advancing rack 133 and moves it one step back, that is, in a direction opposite to the direction of the advancing operation. The coupling 130-B has all the elements of the card advancing coupling 130 and the follower cam 157, which operates the lockout switch, is made wide enough to cooperate with the cam disc 155 of the back-spacer coupling 130-B to open the lockout switch 147 during a back spacing operation in the same way as during the card advancing operation.

Any of the known key actuated operating arrangements of the electromechanical or mechanical type, such as described, for instance, in U. S. Patents 1,969,383, 1,976,352 and 2,044,707, may be utilized for operating the punch selector mechanism and the control arms 109, 137 in order to bring about a predetermined punching operation and immediately thereafter a card carrier advancing operation by the operation of a key.

In the form shown in Figs. 4 to 8, a key actuated mechanical operating arrangement is utilized for automatically controlling the punch selecting and carrier advancing mechanism. It comprises a plurality of key levers 160, each provided with a key button having thereon a proper digit designation, corresponding to the digits of the index columns of the card 20, for instance. Each key lever 160 is pivotally held on the control shaft 110 and is engaged by an underlying lug 161 of an adjacent operating arm 162 affixed, as by a pin, to the control shaft 110, so that a downward tilting motion imparted to the key lever 160 imparts a similar motion to the adjacent lever 162 and thereby actuates the control shaft 110 to impart a corresponding tilting motion to the control arm 109 of the punch operating coupling 90. As a result, the operation of any one of the key buttons "0" to "12" will impart through the adjacent operating arm 162 a corresponding tilting motion to the control arm 105 of the punch operating coupling 90 to set it in operation for performing a punching operation provided the motor 85 is simultaneously energized by the operation of an arm 163 which is likewise affixed to the control shaft 110, and normally holds open the punch actuating switch 146 permitting it to return to the closed position only if it is tilted incident to the tilting motion imparted to the control shaft 110 by a key lever 160.

To an intermediate portion of each key lever 160 is pivotally connected one end of a link 164, the other end of which is pivotally connected to one arm of a bell crank lever 165 pivotally mounted on a bar 166 affixed to the rear side of the punch guide structure 82, and having on its other arm a pin 167 engaging a slot 168 in the punch cam 51 associated with the given key lever, so that on depressing the key lever, the bell crank

165 shifts the desired punch 51 from its normal position to a higher level, in the way explained hereinabove.

Two similarly mounted key levers 160 having key buttons SP and BS, for instance, are similarly pivoted on the control shaft 110 and utilized to actuate the control arms 137, 137-B for operating the card carrier advancing and back spacing couplings 130, 139-B, respectively.

As shown in Figs. 4A, 5 and 12, the front ends 10 of the key levers 160 are guided in slots 171 of a wall 170 on the rear of which is mounted an array of floating levers 172 aligned between two borders 173, the levers being shaped so that their floating ends bar the lower portions of the key-guide slots 171, except the key guide slot, the key of which is depressed, so as to assure that only one key lever 160 can be depressed at a time, and that no other key lever can be depressed while another is in a depressed position.

Means are also provided for automatically locking each key lever 160 when it is actuated to perform a control operation, and keep it locked until it is automatically unlocked when it has performed all required functions which are started by its actuation. In the form shown in Figs. 4A and 12, the locking arrangement is formed by a comblike locking bar 176 slidably mounted on two spacer strips 177 back of the front wall 170 in which the key levers 160 are guided. The locking bar 176 is confined, as by a pin and slot engagement 178, to a limited slidable movement in a direction transverse to the direction of the motion of the key levers, and is biased by a spring 179 to one end position in which the 35 hooked inwardly inner sides of its locking teeth 181 project below the individual key levers 160 extending through the slots of the front wall 170.

When a key lever 160 is actuated to a downward position, its engagement with the underlying tapered surface of a hooked locking tooth 181 shifts the locking bar 176 laterally permitting the key lever to move to its downward position, the locking bar 176 being returned by its biasing spring so as to lock the downwardly actuated key by the bottom surface of the hooked locking tooth 181.

Provision is also made to automatically release a key lever 160 from its locked position at the proper time, after it performed the required functions. In the arrangement shown in Figs. 4A, 5, 11 and 12, this is accomplished by providing the card advancing coupling 130 with a cam plate 183 which is engaged by a cam follower end 184 of a lever 185 pivoted on the control shaft 110 and pivotally connected to a slider bar 186 having a tapered end portion 187 engaging a slot 188 of the lock bar 176 so that when the lever 185 is tilted by the raised portion of the cam plate 183, the tapered end 187 of the slider bar 186 pushes the locking bar 176 against the biasing action of its spring 179 to the position in which it releases the lock key lever 160 which is returned by its biasing spring 112 and extends from the cross bar 113 to its normal upper position.

A key lever 160 that is locked by the locking bar 176 in the depressed condition may be manually released by actuating an unlocking button UL secured to a projection extending from the locking bar 176 so as to push the locking bar against the force of its biasing spring 179 to the unlocking position.

The operation of the machine when used for punching a card will now be described. A card blank 20, such as shown in Fig. 1, is placed on

5 the card carrier 32, which has been previously pulled to the right so that both register pins 33 of the card carrier 32 are to the right of the card retaining finger 43. Thereupon, the card carrier 32, with the card held registered on its pins 33, is moved to the left, either manually or by actuating the advancing key SP, until the first or any other desired index column of the card is brought into alignment with the row of punch bars 51 of the punch carrier. The key corresponding to the information which is to be recorded in the aligned index column of the card, for instance, key 12 in the case of column A of the card shown in Fig. 2, is depressed bringing about a punching operation which removes from the card column A all bridges except bridge 12, and automatically advances the card to bring the index column B into alignment with the punch row.

Cards of any size, three or four times larger 20 than the card 20 indicated in Fig. 5, may be punched on the machine, because all the parts of the mechanism overlying the table plates 34 are held by supports extending from the rear wall of the bed frame 30 so as to leave in front and on the sides of the card carrier 32 a free narrow 25 space through which a large sheet, projecting forwardly beyond the forward end of the machine, may be moved crosswise along the table, with the front end extending beyond the front ends of the keys. This arrangement of the machine makes it possible to make records on cards of any size having any desired number of parallel index position columns.

The record cards 20, such as shown in Figs. 1 and 2, may have the alignment slots 26 made 35 therein either by making the upper and lower hole of the index column longer than the other bridge-forming holes shown in Fig. 1A, by providing in each column, in addition to the bridge-forming holes, separate alignment slots 26A.

The specific exemplification of one form of the invention described above is distinguished not only by various novel structural arrangements, but also by important novel operative principles and arrangements.

45 By combining a record card having index columns formed of bridges separated by interposed bridge-forming perforations with a punching mechanism having a row of punches contiguously aligned opposite the bridges for removing by a punching operation all but one bridge corresponding to the desired information, a simple die member with a simple elongated die slot aligned opposite the row of punches may be used 50 for performing the various desired punching operations, making it unnecessary to use a complicated female die arrangement, while assuring clean-cut properly aligned slots.

55 By making the bridge-forming perforations of slightly greater width than the width of the punch bars, the index column bridges which have to be removed by the punching operation are cut off clean without requiring a high degree of accuracy in aligning the card with the punch mechanism, and a clean-cut punching operation is assured even with a relatively cheaply 60 made aligning mechanism that operates with relatively small degree of accuracy and permits substantial variations of the degree of alignment between the card and the punch mechanism. In the practical arrangement described above, when using record cards in which the perforations interposed between the bridges of the index column are formed by circular holes 70 $\frac{1}{2}$ of an inch in diameter, very satisfactory op-

eration is obtained with punch bars having a width in the direction transverse to the column of the order of 5% less than the diameter of the hole.

A further reduction in the accuracy of the alignment mechanism and its simplification is made possible by combining the row of punches with alignment bars which are arranged to engage alignment holes provided in the facing index column of the record card so as to rectify a minor misalignment of the index column and restore the degree of alignment required to perform a clean-cut punching operation.

In the punching mechanism of the invention, the punches which perform the punching operation in response to the actuation of actuating members, such as a key member, are slidably carried and held contiguously aligned as a punch row on a punch carrier, so as to effect slidable displacement of a selected punch relatively to the other punches from a normal operative position to a retracted non-operative position, punch selector means including a punch displacing element being provided for each punch, so as to operate upon actuation of a key member to produce a relative displacement of the punch and restore the displaced punch to its normal position after performing the punching operation.

The punch mechanism is operated by a power source, and a normally open coupling connection, which operates upon the actuation of an actuating member, to establish a coupling connection during a predetermined punch operating cycle, and bring about the relative motion between the punch carrier and the die member for punching in a predeterminedly aligned position of the card the desired information corresponding to the actuated key member.

The card is held by a card support including a card carrier arranged to be held in one of a plurality of predetermined positions of alignment relatively to the punch mechanism. The card carrier is combined with a card impelling mechanism having a normally open coupling connection to the power source which is operative upon actuation of a key member to establish a coupling connection during a predetermined card impelling cycle and produce a motion of the card carrier so as to bring the card to the next position of alignment.

The power source which supplies the power for performing the punching and card advancing operation has a normally ineffective control circuit and an element, such as a switch, operates upon the actuation of a key member to render the control circuit effective during an operating cycle of the card impelling mechanism or the punch operating mechanism.

The card impelling mechanism is interlocked with the punch operating mechanism so as to prevent the punch operating mechanism from operating if the card carrier is in a position of misalignment.

The punch operating and card impelling mechanisms are so arranged that upon actuation of a key member to record on an index column of a card the desired information, the punch operating and card impelling mechanisms operate in a predetermined sequence so that after performing a punching operation the card is ready to be subjected to the next punching operation in another aligned position of the card.

The principles of the invention described above in connection with one specific exemplification of the invention will suggest various other modi-

fications thereof. Thus, the set of punch bars held contiguously aligned in slidable positions by the punch carrier may be selectively moved between the operative and non-operative positions by other forms of setting or selecting mechanisms, for instance, by providing each punch bar with a pin arranged to engage a cam slot in a flat cam bar extending in a direction parallel to the row of punch bars, the several cam bars being held aligned in a plane parallel and contiguous to the plane of punch bars so that upon selective actuation of one of such cam bars, the corresponding punch bar is moved from one position to the other. Several such rows of punch bars, each with a parallel row of such cam bars, may be mounted in a common punch carrier, and arranged to be selectively set by a key-operated selector mechanism for enabling simultaneous punching of the desired information in adjacent columns of a record card, such as shown in Figs. 1 and 2.

Instead of using an electric motor and a shaft rotated thereby for operating the punch mechanism and card advancing mechanism, electromagnetic mechanisms and escape mechanisms, such as shown in U. S. Patent 1,976,352, may be used.

Instead of controlling the punch selector mechanism through a key-actuated mechanism, the punch setting or selecting mechanism may be controlled by electric relays, for instance, through Bowden wires extending between the relays and the punch bar cams for performing a desired punch displacement operation corresponding to the actuated key, in the way described, for instance, in U. S. Patent 2,044,707.

The card advancing mechanism may be similarly electrically controlled through an electric relay arrangement operating in response to the actuation of a key. Alternatively, the operation of a key may be utilized to mechanically control the operation of the card advancing mechanism and to electrically control the operation of the punch selector mechanism and the punch operating mechanism.

The novel record card and its various features described herein in connection with the exemplifications of the present invention, constitute the subject matter of the application of Cleon E. Shields, Serial No. 451,244, filed July 16, 1942, as a continuation-in-part and division of the present application.

The principles of the invention explained hereinabove in connection with specific exemplifications thereof will suggest to those skilled in the art many other applications and modifications of the same. It is accordingly desired that the appended claims be construed broadly, and that they shall not be limited to the specific details shown and described in connection with the exemplification thereof.

We claim:

1. In a punching machine for punching holes in a record card, a predetermined number of actuating members, such as keys, a punch carrier, at least one row of elongated punches corresponding to the different actuating members carried and held by said punch carrier in a contiguously aligned normal operative position so as to permit displacement of a selected punch from its normal operative position to a displaced position, a die member having a die slot for cooperation with said punches, a card carrier for holding a record card in a predetermined aligned position between said punch carrier and said die

member, punch selector means including a punch displacing element for each punch operative to produce a relative displacement of a punch in response to the actuation of the corresponding actuating member, and punch operating means operative upon actuation of an actuating member to produce a relative motion between said punch carrier and said die member and punch in a predeterminedly aligned position of a card held by said card carrier opening portions facing the punches held in the normal operative position.

2. In a punching machine for punching holes in a record card, a predetermined number of actuating members, such as keys, a punch carrier; at least one row of elongated punches corresponding to the different actuating members carried and held by said punch carrier in a contiguously aligned operative position so as to permit displacement of a selected punch from its operative position to a displaced position; a die member having a die slot for cooperation with said punches, a card carrier for holding a record card in a predetermined aligned position between said punch carrier and said die member, punch selector means including a punch displacing element operative in response to the actuation of an actuating member to actuate a corresponding punch to a displaced position, and punch operating means operative in predetermined relation to the actuation of said corresponding punch to produce a relative motion between said punch carrier and said die member for punching in a predeterminedly aligned position of a card held by said card carrier opening portions facing the punches held in the operative position, and leave intact the portion of the card facing the punch actuated to the displaced position.

3. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a displacing element operative in response to the actuation of a selected actuating member to effect during a predetermined operating cycle a displacement of the corresponding punch from its aligned operative position to its displaced inoperative position; a card carrier for holding a card in a predetermined aligned position relatively to said punches, punch operating means operative upon actuation to actuate during a predetermined operating cycle said punch carrier and said card carrier to move relatively to each other for punching with the punches held in the operative position opening portions in a predeterminedly aligned position of a card held by said card carrier; and means operative in a predetermined manner in response to the actuation of an actuating member for actuating said punch operating means to perform its operating cycle in a predetermined sequence correlated to the operating cycle of said punch selector means so that the punch selector operation is completed before the card is punched.

4. In a punching machine for punching holes in a record card; a predetermined number of actuating members, such as keys; a punch carrier having at least one row of elongated punches

corresponding to the different actuating members movably held by said punch carrier in an aligned operative position so as to permit displacement of a selected punch from its normal operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; a card carrier for holding a card in a predetermined aligned position relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; and means operative in a predetermined manner in response to the actuation of an actuating member for actuating said punch operating means to perform its operating cycle in a predetermined sequence correlated to the operating cycle of said punch selector means so that the punch selector operation is completed before the card is punched.

5. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; and means operative in a predetermined manner in response to the actuation of an actuating member for actuating said punch operating means to perform its operating cycle in a predetermined sequence correlated to the operating cycle of said punch selector means so that the punch selector operation is completed before the card is punched; said punch operating means being so designed and arranged as to cause the elements actuated by it during its operating cycle to be restored to the normal position during a part of its operating cycle.

6. In a punching machine for punching holes in a record card; a predetermined number of actuating members, such as keys; a punch carrier having at least one row of elongated punches corresponding to the different actuating mem-

bers movably held by said punch carrier in an aligned operative position so as to permit displacement of a selected punch from its normal operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; and means operative in a predetermined manner in response to the actuation of an actuating member for actuating said punch operating means to perform its operating cycle in a predetermined sequence correlated to the operating cycle of said punch selector means so that the punch selector operation is completed before the card is punched; said punch selector means and said punch operating means being so designed and arranged as to cause the elements actuated by them during their operating cycles to be restored to the normal position during a part of their operating cycle.

7. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; and means operative in a predetermined manner in response to the actuation of an actuating member for actuating said punch operating means and said card impelling means to perform their operating cycles in a predetermined sequence

correlated in a predetermined manner to the operating cycle of said punch selector means.

8. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; and means operative in a predetermined manner in response to the actuation of an actuating member for actuating said punch operating means and said card impelling means to perform their operating cycles in a predetermined sequence correlated to the operating cycle of said punch selector means so that the punch selector and card impelling operations are completed before the card is punched.

9. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card

impelling means operative upon actuation to produce during a predetermined operating cycle a predetermined relative motion between said punch carrier and said card carrier in a direction transverse to said punch row so as to bring them from one position of alignment to another predetermined position of alignment; and means operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle.

10. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; a 15 card carrier for holding a card in a predetermined aligned position relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; at least one of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means to perform its operating cycle in a predetermined sequence correlated to the operating cycle of said punch selector means so that the punch selector operation is completed before the card is punched.

11. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position; a card carrier for

5 holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; at least one of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means to perform its operating cycle in a predetermined sequence correlated to the operating cycle of said punch selector means so that the punch selector operation is completed before the card is punched; said punch selector means and said punch operating means being so designed and arranged as to cause the elements actuated by them during their operating cycles to be restored to the normal position during a part of their operating cycle.

20 12. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means and said card impelling means to perform their operating cycles in a predetermined sequence correlated in

a predetermined manner to the operating cycle of said punch selector means.

13. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means and said card impelling means to perform their operating cycles in a predetermined sequence correlated to the operating cycle of said punch selector means so that the punch selector and card impelling operations are completed before the card is punched.

14. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle 75

said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means and said card impelling means to perform their operating cycles in a predetermined sequence correlated to the operating cycle of said punch selector means; said punch selector means and said punch operating means being so designed and arranged as to cause the elements actuated by them during their operating cycles to be restored to the normal position during a part of their operating cycle.

15. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; at least one of said operating means being associated with power means including a normally open coupling connection operative to supply operating power to said operating means when said coupling connection is established; and means for establishing said coupling connection operative in a predetermined manner in response to the actuation of an actuating member for actuating said punch operating means to perform its operating cycle in a predetermined sequence correlated to the operating cycle of said punch selector means so that the punch selector operation is completed before the card is punched.

16. In a punching machine for punching holes in a record card; a predetermined number of actuating members, such as keys; a punch carrier having at least one row of elongated punches corresponding to the different actuating mem-

bers movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; at least one of said operating means being associated with power means including a normally open coupling connection operative to supply operating power to said operating means when said coupling connection is established; and means for establishing said coupling connection operative in a predetermined manner in response to the actuation of an actuating member for actuating said punch operating means to perform its operating cycle in a predetermined sequence correlated to the operating cycle of said punch selector means so that the punch selector operation is completed before the card is punched; said punch selector means and said punch operating means being so designed and arranged as to cause the elements actuated by them during their operating cycles to be restored to the normal position during a part of their operating cycle.

17. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of a card impelling means operative upon actuation to produce during a predetermined operating cycle a predetermined relative motion between said punch carrier and said card carrier in a direction transverse to said punch row so as to bring them from one position of alignment

ment to another predetermined position of alignment; at least one of said operating means being associated with power means including a normally open coupling connection operative to supply operating power to said operating means when said coupling connection is established; and means for establishing said coupling connection operative in a predetermined manner in response to the actuation of an actuating member for actuating said punch operating means and said card impelling means to perform their operating cycles in a predetermined sequence correlated in a predetermined manner to the operating cycle of said punch selector means.

18. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally open coupling connection operative to supply operating power to said operating means when said coupling connection is established; and means for establishing said coupling connection operative in a predetermined manner in response to the actuation of an actuating member for actuating said punch operating means and said card impelling means to perform their operating cycles in a predetermined sequence correlated to the operating cycle of said punch selector means so that the punch selector and card impelling operations are completed before the card is punched.

19. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the

actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally open coupling connection operative to supply operating power to said operating means when said coupling connection is established; and means for establishing said coupling connection operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle.

20. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said operating means being associated with power means including a normally open coupling connection and a normally ineffective control circuit operative to supply operating power to said operating means when said coupling connection is established and said control circuit is rendered effective; and means for establishing said coupling connection and for

rendering effective said control circuit operative in a predetermined manner in response to the actuation of an actuating member for actuating said punch operating means to perform its operating cycle in a predetermined sequence correlated to the operating cycle of said punch selector means so that the punch selector operation is completed before the card is punched.

21. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means to perform its operating cycle in a predetermined sequence correlated to the operating cycle of said punch selector means so that the punch selector operation is completed before the card is punched; said punch selector means and said punch operating means being so designed and arranged as to cause the elements actuated by them during their operating cycles to be restored to the normal position during a part of their operating cycle.

22. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of

alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means.

23. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means.

24. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle.

25. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable

displacing element operative in a predetermined manner in response to the actuation of a selected actuating member to effect during a predetermined operating cycle a displacement of the corresponding punch from its aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; at least one of said operating means being associated with normally ineffective power means operative to supply operating power to said operating means when rendered effective; and means for rendering said power means effective operative in a predetermined manner in response to the actuation of an actuating member for actuating said operating means to perform its operating cycle in a predetermined sequence correlated to the operating cycle of the other operating means so that the punch selector operation is completed before the card is punched.

26. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; at least one of said operating means being associated with normally ineffective power means operative to supply operating power to said operating means when rendered effective; and means for rendering said power means effective operative in a predetermined manner in response to the actuation of an actuating member for actuating said operating means to perform its operating cycle in a predetermined sequence correlated to the operating cycle of the other operating means so that the punch selector operation is completed before the card is punched; said punch selector means and said punch operating means being so designed and arranged as to cause the elements actuated by them during their operating cycles to be restored to the normal position during a part of their operating cycle.

27. In a punching machine for punching holes in a record card; a predetermined number of actuating members, such as keys; a punch carrier

having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with normally ineffective power means operative to supply operating power to said operating means when rendered effective; and means for rendering said power means effective operative in a predetermined manner in response to the actuation of an actuating member for actuating said operating means to perform its operating cycle in a predetermined sequence correlated to the operating cycle of the other operating means so that the punch selector and card impelling operations are completed before the card is punched.

28. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch

carrier and said card carrier in a direction transverse to said punch row so as to bring them from one position of alignment to another predetermined position of alignment; at least one of said operating means being associated with normally ineffective power means operative to supply operating power to said operating means when rendered effective; and means for rendering said power means effective operative in a predetermined manner in response to the actuation of an actuating member for actuating said operating means to perform its operating cycle in a predetermined sequence correlated to the operating cycle of the other operating means so that the punch selector and card impelling operations are completed before the card is punched; said punch selector means and said punch operating means being so designed and arranged as to cause the elements actuated by them during their operating cycles to be restored to the normal position during a part of their operating cycle.

29. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with normally ineffective power means operative to supply operating power to said operating means when rendered effective; and means for rendering said power means effective operative in a predetermined manner in response to the actuation of an actuating member for actuating said operating means to perform its operating cycle in a predetermined sequence correlated to the operating cycle of the other operating means so that the punch selector and card impelling operations are completed before the card is punched.

30. In a punching machine for punching holes in a record card; a predetermined number of actuating members, such as keys; a punch carrier having at least one row of elongated punches corresponding to the different actuating members movably held by said punch carrier in an aligned operative position so as to permit displacement

of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with normally ineffective power means operative to supply operating power to said operating means when rendered effective; and means for rendering said power means effective operative in a predetermined manner in response to the actuation of an actuating member for actuating said operating means to perform its operating cycle in a predetermined sequence correlated to the operating cycle of the other operating means so that the punch selector and card impelling operations are completed before the card is punched; said punch selector means and said punch operating means being so designed and arranged as to cause the elements actuated by them during their operating cycles to be restored to the normal position during a part of their operating cycle.

31. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative

upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means.

32. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means so that the punch selector and card impelling operations are completed before the card is punched.

33. In a punching machine for punching holes in a record card; a predetermined number of actuating members, such as keys; a punch carrier having at least one row of elongated punches corresponding to the different actuating members movably held by said punch carrier in an aligned

operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle.

34. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card car-

rier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally open coupling connection operative to supply operating power to said operating means when said coupling connection is established; and means for establishing said coupling connection operative in a predetermined manner in response to the actuation of an actuating member for actuating said punch operating means and said card impelling means to perform their operating cycles in a predetermined sequence correlated in a predetermined manner to the operating cycle of said punch selector means.

35. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally open coupling connection operative to supply operating power to said operating means when said coupling connection is established; and means for establishing said coupling connection operative in a predetermined manner in response to the actuation of an actuating member for actuating said punch operating means and said card impelling means to perform their operating cycles in a predetermined sequence correlated in a predetermined manner to the operating cycle of said punch selector means so that the punch selector and card impelling operations are completed before the card is punched.

36. In a punching machine for punching holes in a record card; a predetermined number of actuating members, such as keys; a punch carrier having at least one row of elongated punches corresponding to the different actuating members movable held by said punch carrier in an

aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally open coupling connection operative to supply operating power to said operating means when said coupling connection is established; and means for establishing said coupling connection operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle.

37. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally open coupling connection operative to supply operating power to said operating means when said coupling connection is established; and means for establishing said coupling connection operative in a predetermined manner in response to the actuation of an actuating member for actuating said punch operating means and said card impelling means to perform their operating cycles in a predetermined sequence correlated in a predetermined manner to the operating cycle of said punch selector means so that the punch selector and card impelling operations are completed before the card is punched.

aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means.

38. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated to the operating cycle of said punch selector means so

that the punch selector and card impelling operations are completed before the card is punched.

39. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle.

40. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inop-

erative position; a card carrier for holding a card in a predetermined aligned position relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means to perform its operating cycle in a predetermined sequence correlated to the operating cycle of said punch selector means so that the punch selector operation is completed before the card is punched; said control circuit having an element actuated by the operation of said coupling means for rendering said control circuit effective during an operating cycle of said operating means.

41. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means to perform its operating cycle in a predetermined sequence correlated to the operating cycle of said punch selector means so that the punch selector operation is completed before the card is punched; said punch selector means and said punch operating means being so designed and arranged as to cause the elements

5 actuated by them during their operating cycles to be restored to the normal position during a part of their operating cycle; said control circuit having an element actuated by the operation of said coupling means for rendering said control circuit effective during an operating cycle of said operating means.

42. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means; said control circuit having an element actuated by the operation of said coupling means for rendering said control circuit effective during an operating cycle of said operating means.

43. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means; said control circuit having an element actuated by the operation of said coupling means for rendering said control circuit effective during an operating cycle of said operating means.

member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle 10 said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle; said control circuit having an element actuated by the operation of said coupling means for rendering said control circuit effective during an operating cycle of said operating means.

44. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch

carrier and said card carrier in a direction transverse to said punch row so as to bring them from one position of alignment to another predetermined position of alignment; said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle; said control circuit having an element actuated by the operation of said coupling means for rendering said control circuit effective during an operating cycle of said operating means.

45. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating

cycles in a predetermined sequence correlated in a predetermined manner to the operating cycle of said punch selector means; said control circuit having an element actuated by the operation of said coupling means for rendering said control circuit effective during an operating cycle of said operating means.

46. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated to the operating cycle of said punch selector means so that the punch selector and card impelling operations are completed before the card is punched; said control circuit having an element actuated by the operation of said coupling means for rendering said control circuit effective during an operating cycle of said operating means.

47. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actu-

ation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least two of said operating means being associated with power means including a normally open coupling connection and a normally ineffective control circuit operative to supply operating power to said operating means when said coupling connection is established and said control circuit is rendered effective; and means for establishing said coupling connection and for rendering effective said control circuit operative in a predetermined manner in response to the actuation of an actuating member for actuating said punch operating means and said card impelling means to perform their operating cycles in a predetermined sequence correlated to the operating cycle of said punch selector means; said punch selector means and said punch operating means being so designed and arranged as to cause the elements actuated by them during their operating cycles to be restored to the normal position during a part of their operating cycle; said control circuit having an element actuated by the operation of said coupling means for rendering said control circuit effective during an operating cycle of said operating means.

48. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a displacing element operative in response to the actuation of a selected actuating member to effect during a predetermined operating cycle a displacement of the corresponding punch from its aligned operative position to its displaced inoperative position; a card carrier for holding a card in a predetermined aligned position relatively to said punches; punch operating means operative upon actuation to actuate during a predetermined operating cycle said punch carrier and said card carrier to move relatively to each other for punching with the punches held in the operative position opening portions in a predeterminedly aligned position of a card held by said card carrier; and means operative in a predetermined manner in response to the actuation of an actu-

ating member for actuating said punch operating means to perform its operating cycle in a predetermined sequence correlated to the operating cycle of said punch selector means so that the punch selector operation is completed before the card is punched; said punch operating means and said card carrier being so designed and correlated as to prevent said punch operating means from being effective if said card carrier is in an out-of-alignment position.

49. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; and means operative in a predetermined manner in response to the actuation of an actuating member for actuating said punch operating means to perform its operating cycle in a predetermined sequence correlated to the operating cycle of said punch selector means so that the punch selector operation is completed before the card is punched; said punch selector means and said punch operating means being so designed and arranged as to cause the elements actuated by them during their operating cycles to be restored to the normal position during a part of their operating cycle; said punch operating means and said card carrier being so designed and correlated as to prevent said punch operating means from being effective if said card carrier is in an out-of-alignment position.

50. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; a card carrier for holding a card in a predetermined aligned position relatively to said punches; said punch carrier being part of punch operating means operative upon actuation to actuate during a predetermined operating cycle said punch

carrier and said card carrier to move relatively to each other for punching with the punches held in the operative position opening portions in a predeterminedly aligned position of a card held by said card carrier; at least one of said operating means being associated with normally ineffective power means operative to supply operating power to said operating means when rendered effective; and means for rendering said power means effective operative in a predetermined manner in response to the actuation of an actuating member for actuating said operating means to perform its operating cycle in a predetermined sequence correlated to the operating cycle of the other operating means so that the punch selector operation is completed before the card is punched; said punch operating means and said card carrier being so designed and correlated as to prevent said punch operating means from being effective if said card carrier is in an out-of-alignment position.

51. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selective punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; at least one of said operating means being associated with normally ineffective power means operative to supply operating power to said operating means when rendered effective; and means for rendering said power means effective operative in a predetermined manner in response to the actuation of an actuating member for actuating said operating means to perform its operating cycle in a predetermined sequence correlated to the operating cycle of the other operating means so that the punch selector operation is completed before the card is punched; said punch selector means and said punch operating means being so designed and arranged as to cause the elements actuated by them during their operating cycles to be restored to the normal position during a part of their operating cycle; said punch operating means and said card carrier being so designed and correlated as to prevent said punch operating means from being effective if said card carrier is in an out-of-alignment position.

52. In a punching machine for punching holes in a record card; a predetermined number of actuating members, such as keys; a punch carrier having at least one row of elongated punches corresponding to the different actuating members movably held by said punch carrier in an

aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; and means operative in a predetermined manner in response to the actuation of an actuating member for actuating said punch operating means and said card impelling means to perform their operating cycles in a predetermined sequence correlated in a predetermined manner to the operating cycle of said punch selector means; said punch operating means and said card impelling means being so designed and correlated as to prevent said punch operating means from being effective if said card carrier is in an out-of-alignment position.

53. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to

another predetermined position of alignment; and means operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle; said punch operating means and said card impelling means being so designed and correlated as to prevent said punch operating means from being effective if said card carrier is in an out-of-alignment position.

54. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means and said card impelling means to perform their operating cycles in a predetermined sequence correlated in a predetermined manner to the operating cycle of said punch selector means; said punch operating means and said card impelling means being so designed and correlated as to include an element actuated by said card impelling means operative to prevent said punch operating means from being effective if said card carrier is in an out-of-alignment position.

55. In a punching machine for punching holes in a record card; a predetermined number of actuating members, such as keys; a punch carrier having at least one row of elongated punches cor-

responding to the different actuating member movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means and said card impelling means to perform their operating cycles in a predetermined sequence correlated to the operating cycle of said punch selector means so that the punch selector and card impelling operations are completed before the card is punched; said punch operating means and said card impelling means being so designed and correlated as to include an element actuated by said card impelling means operative to prevent said punch operating means from being effective if said card carrier is in an out-of-alignment position.

56. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle 75

said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally ineffective control circuit operative to supply operating power to said operating means when said control circuit is rendered effective; and means for rendering effective said control circuit operative in a predetermined manner in response to the actuation of an actuating member for actuating said punch operating means and said card impelling means to perform their operating cycles in a predetermined sequence correlated to the operating cycle of said punch selector means; said punch selector means and said punch operating means being so designed and arranged as to cause the elements actuated by them during their operating cycles to be restored to the normal position during a part of their operating cycle; said punch operating means and said card impelling means being so designed and correlated as to include an element actuated by said card impelling means operative to prevent said punch operating means from being effective if said card carrier is in an out-of-alignment position.

57. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally open coupling connection operative to supply operating power to said operating means when said coupling con-

nection is established; and means for establishing said coupling connection operative in a predetermined manner in response to the actuation of an actuating member for actuating said punch operating means and said card impelling means to perform their operating cycles in a predetermined sequence correlated in a predetermined manner to the operating cycle of said punch selector means; said punch operating means and said card impelling means being so designed and correlated as to include an element actuated by said card impelling means operative to prevent said punch operating means from being effective if said card carrier is in an out-of-alignment position.

58. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally open coupling connection operative to supply operating power to said operating means when said coupling connection is established; and means for establishing said coupling connection operative in a predetermined manner in response to the actuation of an actuating member for actuating said punch operating means and said card impelling means to perform their operating cycles in a predetermined sequence correlated to the operating cycle of said punch selector means so that the punch selector and card impelling operations are completed before the card is punched; said punch operating means and said card impelling means being so designed and correlated as to include an element actuated by said card impelling means operative to prevent said punch operating means from being effective if said card carrier is in an out-of-alignment position.

59. In a punching machine for punching holes in a record card; a predetermined number of actuating members, such as keys; a punch carrier having at least one row of elongated punches corresponding to the different actuating members

movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with power means including a normally open coupling connection operative to supply operating power to said operating means when said coupling connection is established; and means for establishing said coupling connection operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle; said punch operating means and said card impelling means being so designed and correlated as to include an element actuated by said card impelling means operative to prevent said punch operating means from being effective if said card carrier is in an out-of-alignment position.

60. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector operating means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said

punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with normally ineffective power means operative to supply operating power to said operating means when rendered effective; and means for rendering said power means effective operative in a predetermined manner in response to the actuation of an actuating member for actuating said operating means to perform its operating cycle in a predetermined sequence correlated to the operating cycle of the other operating means so that the punch selector and card impelling operations are completed before the card is punched; said punch operating means and said card impelling means being so designed and correlated as to include an element actuated by said card impelling means operative to prevent said punch operating means from being effective if said card carrier is in an out-of-alignment position.

61. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector operating means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; at least one of said operating means being associated with normally ineffective power means operative to supply operating power to said operating means when rendered effective; and means for rendering said power means ef-

5 fective operative in a predetermined manner in response to the actuation of an actuating member for actuating said operating means to perform its operating cycle in a predetermined sequence correlated to the operating cycle of the other operating means so that the punch selector and card impelling operations are completed before the card is punched; said punch selector means and said punch operating means being so designed and arranged as to cause the elements actuated by them during their operating cycles to be restored to the normal position during a part of their operating cycle; said punch operating means and said card impelling means being so designed and correlated as to include an element actuated by said card impelling means operative to prevent said punch operating means from being effective if said card carrier is in an out-of-alignment position.

20 62. In a punching machine for punching holes in a record card, a predetermined number of actuating members, such as keys; a punch carrier; at least one row of elongated punches corresponding to the different actuating members carried and held by said punch carrier in a contiguously aligned operative position so as to permit displacement of a selected punch from its operative position to a displaced position; a die member having a die slot for cooperation with said punches, a card carrier for holding a record card in a predetermined aligned position between said punch carrier and said die member, punch selector means including a punch displacing element operative in response to the actuation of an actuating member to actuate a corresponding punch to a displaced position, and punch operating means operative in predetermined relation to the actuation of said corresponding punch to produce a relative motion between said punch carrier and said die member for punching in a predeterminedly aligned position of a card held by said card carrier opening portions facing the punches held in the operative position, and leave intact the portion of the card facing the punch actuated to the displaced position; and at least one alignment member associated with said punches arranged to be actuated during a punch operating cycle to engage a card subjected to a punching operation before the card is punched for keeping said card aligned with said punch row during the punching operation.

45 63. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a displacing element operative in response to the actuation of a selected actuating member to effect during a predetermined operating cycle a displacement of the corresponding punch from its aligned operative position to its displaced inoperative position; a card carrier for holding a card in a predetermined aligned position relatively to said punches, punch operating means operative upon actuation to actuate during a predetermined operating cycle said punch carrier and said card carrier to move relatively to each other for punching with the punches held in the operative position opening portions in a predeterminedly aligned position of a card held

by said card carrier; means operative in a predetermined manner in response to the actuation of an actuating member for actuating said punch operating means to perform its operating cycle in a predetermined sequence correlated to the operating cycle of said punch selector means so that the punch selector operation is completed before the card is punched; and at least one alignment member carried by said punch carrier arranged to be actuated during a punch operating cycle to engage a card subjected to a punching operation before the card is punched for keeping said card aligned with said punch row during the punching operation.

64. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; means operative in a predetermined manner in response to the actuation of an actuating member for actuating said punch operating means to perform its operating cycle in a predetermined sequence correlated to the operating cycle of said punch selector means so that the punch selector operation is completed before the card is punched; said punch selector means and said punch operating means being so designed and arranged as to cause the elements actuated by them during their operating cycles to be restored to the normal position during a part of their operating cycle; and at least one alignment member associated with said punches arranged to be actuated during a punch operating cycle to engage a card subjected to a punching operation before the card is punched for keeping said card aligned with said punch row during the punching operation.

65. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned opera-

tive position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member arranged to be actuated during a punch operating cycle to engage a card subjected to a punching operation before the card is punched for keeping said card aligned with said punch row during the punching operation.

66. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member car-

ried by said punch carrier arranged to be actuated during a punch operating cycle to engage a card subjected to a punching operation before the card is punched for keeping said card aligned with said punch row during the punching operation.

67. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member held in a predetermined alignment relation to said punches and arranged to be actuated during a punch operating cycle to engage a card subjected to a punching operation before the card is punched for keeping said card aligned with said punch row during the punching operation.

68. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member carried by said punch carrier arranged to be actuated during a punch operating cycle to engage a card subjected to a punching operation before the card is punched for keeping said card aligned with said punch row during the punching operation.

being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member associated with said punches arranged to be actuated during a punch operating cycle to engage a card subjected to a punching operation before the card is punched for keeping said card aligned with said punch row during the punching operation.

69. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member carried by said punch carrier arranged to be actuated during a punch operating cycle to engage a card subjected to a punching operation before the card is punched for keeping said card aligned with said punch row during the punching operation.

70. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle; and at least one alignment member associated with said punches arranged to be actuated during a punch operating cycle to engage a card subjected to a punching operation before the card is punched for keeping said card aligned with said punch row during the punching operation.

71. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their

held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle; and at least one alignment member associated with said punches arranged to be actuated during a punch operating cycle to engage a card subjected to a punching operation before the card is punched for keeping said card aligned with said punch row during the punching operation.

30 72. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their

operating cycles to be restored to the normal position during a part of their operating cycle; and at least one alignment member carried by said punch carrier arranged to be actuated during a punch operating cycle to engage a card subjected to a punching operation before the card is punched for keeping said card aligned with said punch row during the punching operation.

73. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position and to restore the displaced punch to its normal position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predeterminedly aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; said punch selector means and said punch operating means being so designed and arranged as to cause the elements actuated by them during their operating cycles to be restored to the normal position during a part of their operating cycle; and at least one alignment member associated with said punches held in a predetermined alignment relation to said punches and arranged to be actuated during a punch operating cycle to engage a card subjected to a punching operation before the card is punched for keeping said card aligned with said punch row during the punching operation.

74. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a displacing ele-

ment operative in response to the actuation of a selected actuating member to effect during a predetermined operating cycle a displacement of the corresponding punch from its aligned operative position to its displaced inoperative position; a card carrier for holding a card in a predetermined aligned position relatively to said punches; punch operating means operative upon actuation to actuate during a predetermined operating cycle said punch carrier and said card carrier to move relatively to each other for punching with the punches held in the operative position opening portions in a predeterminedly aligned position of a card held by said card carrier; and means operative in a predetermined manner in response to the actuation of an actuating member for actuating said punch operating means to perform its operating cycle in a predetermined sequence correlated to the operating cycle of said punch selector means so that the punch selector operation is completed before the card is punched; a guide structure for supporting and guiding said punch carrier during a punching operation, and forming an operative support for said actuating members and said punch operating means.

75. In a punching machine for punching holes in a record card; a predetermined number of actuating members, such as keys; a punch carrier having at least one row of elongated punches corresponding to the different actuating members movably held by said punch carrier in an aligned operative position so as to permit displacement of a selected punch from its normal operative aligned position to an inoperative displaced position; punch selector means including a movable displacing element operative in a predetermined manner in response to the actuation of a selected actuating member to effect during a predetermined operating cycle a displacement of the corresponding punch from its normal aligned operative position to its displaced inoperative position; a card carrier for holding a card in a predetermined aligned position relatively to said punches; said punch carrier being part of punch operating means operative upon actuation to actuate during a predetermined operating cycle said punch carrier and said card carrier to move relatively to each other from a normal position to a punching position for punching with the punches held in the operative position opening portions in a predeterminedly aligned position of a card held by said card carrier; means operative in a predetermined manner in response to the actuation of an actuating member for actuating said punch operating means to perform its operating cycle in a predetermined sequence correlated to the operating cycle of said punch selector means so that the punch selector operation is completed before the card is punched; said punch selector means and said punch operating means being so designed and arranged as to cause the elements actuated by them during their operating cycles to be restored to the normal position during a part of their operating cycle; and a guide structure for supporting and guiding said punch carrier during a punching operation, and forming an operative support for said actuating members and said punch operating means.

76. In a punching machine for punching holes in a record card; a predetermined number of actuating members, such as keys; a punch carrier having at least one row of elongated punches corresponding to the different actuating members

movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; and means operative in a predetermined manner in response to the actuation of an actuating member for actuating said punch operating means and said card impelling means to perform their operating cycles in a predetermined sequence correlated in a predetermined manner to the operating cycle of said punch selector means; a guide structure for supporting and guiding said punch carrier during a punching operation, and forming an operative support for said actuating members, said card impelling means and said punch operating means.

77. The combination of a record card formed with a plurality of parallel index columns, each column being subdivided into a plurality of index positions formed by bridges separated by openings so that a single predetermined bridge left in a column from which the other bridges have been removed represents the information recorded in the column, said card having at least one aligning opening correlated in a predetermined manner to said columns for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a displacing element operative in response to the actuation of a selected actuating member to effect during a predetermined operating cycle a displacement of the corresponding punch from its aligned operative position to its displaced inoperative position; a card carrier for holding a card in a predetermined aligned position relatively to said punches; punch operating means operative upon actuation to actuate during a predetermined operating cycle said punch carrier and said card carrier to move relatively to each other for punching with the punches held in the operative position opening portions in a predetermined aligned position of a card held by said card carrier; means operative in a predetermined manner in response to the actuation of an actuating member for actuating said punch operating means to perform its operating cycle in a predetermined sequence correlated to the operating cycle of said punch selector means so that the punch selector operation is completed before the card is punched; and at least one alignment member carried by said punch carrier arranged to be actuated during a punch operating cycle to engage an aligning opening of the card when it is subjected to a punching operation before the card is punched for keeping said card aligned with said punch row during the punching operation.

each other for punching with the punches held in the operative position opening portions in a predeterminedly aligned position of a card held by said card carrier; means operative in a predetermined manner in response to the actuation of an actuating member for actuating said punch operating means to perform its operating cycle in a predetermined sequence correlated to the operating cycle of said punch selector means so that the punch selector operation is completed before the card is punched; and at least one alignment member carried by said punch carrier arranged to be actuated during a punch operating cycle to engage an aligning opening of the card when it is subjected to a punching operation before the card is punched for keeping said card aligned with said punch row during the punching operation.

78. The combination of a record card formed with a plurality of parallel index columns, each column being subdivided into a plurality of index positions formed by bridges separated by openings so that a single predetermined bridge left in a column from which the other bridges have been removed represents the information recorded in the column, each column of said card having at least one aligning opening correlated in a predetermined manner to said column for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a displacing element operative in response to the actuation of a selected actuating member to effect during a predetermined operating cycle a displacement of the corresponding punch from its aligned operative position to its displaced inoperative position; a card carrier for holding a card in a predetermined aligned position relatively to said punches; punch operating means operative upon actuation to actuate during a predetermined operating cycle said punch carrier and said card carrier to move relatively to each other for punching with the punches held in the operative position opening portions in a predeterminedly aligned position of a card held by said card carrier; means operative in a predetermined manner in response to the actuation of an actuating member for actuating said punch operating means to perform its operating cycle in a predetermined sequence correlated to the operating cycle of said punch selector means so that the punch selector operation is completed before the card is punched; and at least one alignment member carried by said punch carrier arranged to be actuated during a punch operating cycle to engage an aligning opening of the card when it is subjected to a punching operation before the card is punched for keeping said card aligned with said punch row during the punching operation.

79. The combination of a record card formed with a plurality of parallel index columns, each column being subdivided into a plurality of index positions formed by bridges separated by openings so that a single predetermined bridge

left in a column from which the other bridges have been removed represents the information recorded in the column, the upper and lower end of each column of said card having an aligning opening correlated in a predetermined manner to said column for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a displacing element operative in response to the actuation of a selected actuating member to effect during a predetermined operating cycle a displacement of the corresponding punch from its aligned operative position to its displaced inoperative position; a card carrier for holding a card in a predetermined aligned position relatively to said punches; punch operating means operative upon actuation to actuate during a predetermined operating cycle said punch carrier and said card carrier to move relatively to each other for punching with the punches held in the operative position opening portions in a predeterminedly aligned position of a card held by said card carrier; means operative in a predetermined manner in response to the actuation of an actuating member for actuating said punch operating means to perform its operating cycle in a predetermined sequence correlated to the operating cycle of said punch selector means so that the punch selector operation is completed before the card is punched; and at least one alignment member carried by said punch carrier arranged to be actuated during a punch operating cycle to engage an aligning opening of the card when it is subjected to a punching operation before the card is punched for keeping said card aligned with said punch row during the punching operation.

80. The combination of a record card formed with a plurality of parallel index columns, each column being subdivided into a plurality of index positions formed by bridges separated by openings so that a single predetermined bridge left in a column from which the other bridges have been removed represents the information recorded in the column, at least one of the openings forming the end of a column being elongated so as to serve as an aligning opening for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a displacing element operative in response to the actuation of a selected actuating member to effect during a predetermined operating cycle a displacement of the correspond-

ing punch from its aligned operative position to its displaced inoperative position; a card carrier for holding a card in a predetermined aligned position relatively to said punches; punch operating means operative upon actuation to actuate during a predetermined operating cycle said punch carrier and said card carrier to move relatively to each other for punching with the punches held in the operative position opening portions in a predeterminedly aligned position of a card held by said card carrier; means operative in a predetermined manner in response to the actuation of an actuating member for actuating said punch operating means to perform its operating cycle in a predetermined sequence correlated to the operating cycle of said punch selector means so that the punch selector operation is completed before the card is punched; and at least one alignment member carried by said punch carrier arranged to be actuated during a punch operating cycle to engage an aligning opening of the card when it is subjected to a punching operation before the card is punched for keeping said card aligned with said punch row during the punching operation.

81. The combination of a record card formed with a plurality of parallel index columns, each column being subdivided into a plurality of index positions formed by bridges separated by openings so that a single predetermined bridge left in a column from which the other bridges have been removed represents the information recorded in the column, said card having at least one aligning opening correlated in a predetermined manner to said columns for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for ac-

tuating said punch operating means and said card impelling means to perform their operating cycles in a predetermined sequence correlated in a predetermined manner to the operating cycle of said punch selector means; and at least one alignment member associated with said punches arranged to be actuated during a punch operating cycle to engage an aligning opening of the card when it is subjected to a punching operation before the card is punched for keeping said card aligned with said punch row during the punching operation.

82. The combination of a record card formed with a plurality of parallel index columns, each column being subdivided into a plurality of index positions formed by bridges separated by openings so that a single predetermined bridge left in a column from which the other bridges have been removed represents the information recorded in the column, each column of said card having at least one aligning opening correlated in a predetermined manner to said column for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member associated with said punches arranged to be actuated during a punch operating cycle to engage an aligning opening of the card when it is subjected to a punching operation before the card is punched for keeping said card aligned with said punch row during the punching operation.

83. The combination of a record card formed 75

with a plurality of parallel index columns, each column being subdivided into a plurality of index positions formed by bridges separated by openings so that a single predetermined bridge left in a column from which the other bridges have been removed represents the information recorded in the column, the upper and lower end of each column of said card having an aligning opening correlated in a predetermined manner to said column for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member associated with said punches arranged to be actuated during a punch operating cycle to engage an aligning opening of the card when it is subjected to a punching operation before the card is punched for keeping said card aligned with said punch row during the punching operation.

84. The combination of a record card formed with a plurality of parallel index columns, each column being subdivided into a plurality of index positions formed by bridges separated by openings so that a single predetermined bridge left in a column from which the other bridges have been removed represents the information recorded in the column, at least one of the openings forming the end of a column being elongated so as to serve as an aligning opening for keeping the card aligned during the removal of bridges while making a record in a column; with a punching machine for selectively punching at least one column of a card so as to record information therein.

said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined different positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member associated with said punches arranged to be actuated during a punch operating cycle to engage an aligning opening of the card when it is subjected to a punching operation before the card is punched for keeping said card aligned with said punch row during the punching operation.

85. The combination of a record card formed with a plurality of parallel index columns, each column being subdivided into a plurality of index positions formed by bridges separated by openings so that a single predetermined bridge left in a column from which the other bridges have been removed represents the information recorded in the column, said card having at least one aligning opening correlated in a predetermined manner to said columns for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being

5 active position to its displaced inoperative position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member associated with said punches arranged to be actuated during a punch operating cycle to engage an aligning opening of the card when it is subjected to a punching operation before the card is punched for keeping said card aligned with said punch row during the punching operation.

35 86. The combination of a record card formed with a plurality of parallel index columns, each column being subdivided into a plurality of index positions formed by bridges separated by openings so that a single predetermined bridge left in a column from which the other bridges have been removed represents the information recorded in the column, each column of said card having at least one aligning opening correlated in a predetermined manner to said column for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being

part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member associated with said punches arranged to be actuated during a punch operating cycle to engage an aligning opening of the card when it is subjected to a punching operation before the card is punched for keeping said card aligned with said punch row during the punching operation.

87. The combination of a record card formed with a plurality of parallel index columns, each column being subdivided into a plurality of index positions formed by bridges separated by openings so that a single predetermined bridge left in a column from which the other bridges have been removed represents the information recorded in the column, the upper and lower end of each column of said card having an aligning opening correlated in a predetermined manner to said column for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member associated with said punches arranged to be actuated during a punch operating cycle to engage an aligning opening of the card when it is subjected to a punching operation before the card is punched for keeping said card aligned with said punch row during the punching operation.

manner to the operating cycle of said punch selector means; and at least one alignment member associated with said punches arranged to be actuated during a punch operating cycle to engage an alignment opening of the card when it is subjected to a punching operation before the card is punched for keeping said card aligned with said punch row during the punching operation.

88. The combination of a record card formed with a plurality of parallel index columns, each column being subdivided into a plurality of index positions formed by bridges separated by openings so that a single predetermined bridge left in a column from which the other bridges have been removed represents the information recorded in the column, at least one of the openings forming the end of a column being elongated so as to serve as an aligning opening for keeping the card aligned during the removal of bridges while making a record in a column; with a punching machine for selectively punching at least one column of a card so as to record information therein, said machine comprising a predetermined number of actuating members, such as keys; a punch carrier having at least one row of elongated punches corresponding to the different actuating members movably held by said punch carrier in an aligned operative position so as to permit displacement of a selected punch from its operative aligned position to an inoperative displaced position; punch selector means including a movable displacing element operative in a predetermined manner in response to the actuation of a selected actuating member to effect during a predetermined operating cycle a displacement of the corresponding punch from its aligned operative position to its displaced inoperative position; card support means including a card carrier for holding a card in one of a plurality of predetermined successive positions of alignment relatively to said punches; said punch carrier being part of punch operating means operative upon actuation to actuate during a predetermined operating cycle said punch carrier and said card carrier to move relatively to each other for punching with the punches held in the operative position opening portions in a predetermined aligned position of a card held by said card carrier; said card carrier being part of card impelling means operative upon actuation to produce during a predetermined operating cycle a predetermined relative motion between said punch carrier and said card carrier in a direction transverse to said punch row so as to bring them from one position of alignment to another predetermined position of alignment; means operative in a predetermined manner in response to the actuation of an actuating member for actuating said punch operating means and said card impelling means to perform their operating cycles in a predetermined sequence correlated in a predetermined manner to the operating cycle of said punch selector means; and at least one alignment member associated with said punches arranged to be actuated during a punch operating cycle to engage an aligning opening of the card when it is subjected to a punching operation before the card is punched for keeping said card aligned with said punch row during the punching operation.

89. In a punching machine for punching holes in a record card; a predetermined number of actuating members, such as keys; a punch carrier; at least one row of elongated punches cor-

responding to said different actuating members and guided by said punch carrier so as to permit a predetermined movement of a selected punch between a punching position and a non-punching position; a die member having opening portions for cooperation with said punches; a card carrier for holding a record card in a predetermined aligned position between said punch carrier and said die member; punch setting means including a punch displacing element operative in response to the actuation of an actuating member to set said row of punches so that the corresponding punch is held in a non-punching position and the other punches are held in punching positions; and punch operating means operative for producing a relative motion between said punch carrier and said die member and punching in a predeterminedly aligned position of a card held by said card carrier opening portions facing the punches held in the punching position, and leave intact a portion of the card facing a punch held in the non-punching position; said punch setting means and said punch operating means including means operative in response to the actuation of an actuating member to cause them to perform their respective operating cycles in a predetermined correlated sequence so that the punch setting operation is completed before the card is punched.

90. The combination—of a record card formed with a plurality of parallel index columns which are subdivided into a plurality of index positions formed by bridge elements so that a single predetermined bridge element left in a column from which the other bridge elements have been removed represents the information recorded in the column—with a punching machine for selectively punching at least one column of a card so as to record information therein; said card having at least one aligning opening correlated in a predetermined manner to said columns for keeping the card aligned during the removal of the bridge elements while making a record in a column; said machine comprising a predetermined number of actuating members, such as keys, a punch carrier, at least one row of elongated punches corresponding to the different actuating members carried by said punch carrier so as to permit a predetermined movement of a selected punch between a punching position and a non-punching position, a die member having opening portions for cooperation with said punches, a card carrier for holding a record card in a predetermined aligned position between said punch carrier and said die member, punch operating means operative upon actuation of an actuating member to actuate said punch carrier to punch with the punches held in the punching position opening portions in a predetermined aligned column position of a card held by said card carrier, and at least one alignment member carried by said punch carrier and arranged to be actuated during a punch operating cycle to engage an aligning opening of the card before it is punched so as to keep a predetermined column of the card aligned with said punch row during the punching operation.

91. The combination—of a record card formed with a plurality of parallel index columns which are subdivided into a plurality of index positions formed by bridge elements so that a single predetermined bridge element left in a column from which the other bridge elements have been removed represents the information recorded in the column—with a punching machine for selec-

tively punching at least one column of a card so as to record information therein; each of said columns having at least one aligning opening correlated in a predetermined manner to said column for keeping the card aligned during the removal of the bridge elements while making a record in a column; said machine comprising a predetermined number of actuating members, such as keys, a punch carrier, at least one row of elongated punches corresponding to the different actuating members carried by said punch carrier so as to permit a predetermined movement of a selected punch between a punching position and a non-punching position, a die member having opening portions for cooperation with said punches, card carrier means including a card carrier for holding a record card in a predetermined aligned position between said punch carrier and said die member and card impelling means operative to impel the card carrier to successive aligned positions, punch operating means operative upon actuation of an actuating member to actuate said punch carrier to punch with the punches held in the punching position opening portions in a predetermined aligned column position of a card held by said card carrier, means operative in a predetermined manner in response to the actuation of an actuating member for actuating said card impelling

92. The combination—of a record card formed with a plurality of parallel index columns which are subdivided into a plurality of index positions formed by bridge elements so that a single predetermined bridge element left in a column from which the other bridge elements have been removed represents the information recorded in the column—with a punching machine for selectively punching at least one column of a card so as to record information therein; the upper and lower ends of said card having an aligning opening correlated in a predetermined manner to said columns for keeping the card aligned during the removal of the bridge elements while making a record in a column; said machine comprising a predetermined number of actuating members, such as keys, a punch carrier, at least one row of elongated punches corresponding to the different actuating members carried by said punch carrier so as to permit a predetermined movement of a selected punch between a punching position and a non-punching position, a die member having opening portions for cooperation with said punches, card carrier means including a card carrier for holding a record card in a predetermined aligned position between said punch carrier and said die member and card impelling means operative to impel the card carrier to successive aligned positions, punch operating means operative upon actuation of an actuating member to actuate said punch carrier to punch with the punches held in the punching position opening portions in a predetermined aligned column position of a card held by said card carrier, means operative in a predetermined manner in response to the actuation of an actuating member for actuating said card impelling

means to perform its operating cycle in a predetermined sequence correlated to the operating cycle of said punch operating means, and two alignment members carried by said punch carrier and arranged to be actuated during a punch operating cycle to engage an aligning opening of the card before it is punched so as to keep a predetermined column of the card aligned with said punch row during the punching operation.

93. The combination—of a record card formed with a plurality of parallel index columns which are subdivided into a plurality of index positions formed by bridge elements separated by openings so that a single predetermined bridge element left in a column from which the other bridge elements have been removed represents the information recorded in the column—with a punching machine for selectively punching at least one column of a card so as to record information therein; at least one of the openings forming the end of a column being elongated so as to serve as an aligning opening correlated in a predetermined manner to said column for keeping the card aligned during the removal of the bridge elements while making a record in a column; said machine comprising a predetermined number of actuating members, such as keys, a punch carrier, at least one row of elongated punches corresponding to the different actuating members carried by said punch carrier so as to permit a predetermined movement of a selected punch between a punching position and a non-punching position, a die member having opening portions for cooperation with said punches, card carrier means including a card carrier for holding a record card in a predetermined aligned position between said punch carrier and said die member and card impelling means operative to impel the card carrier to successive aligned positions, punch operating means operative upon actuation of an actuating member to actuate said punch carrier to punch with the punches held in the punching position opening portions in a predetermined aligned column position of a card held by said card carrier, means operative in a predetermined manner in response to the actuation of an actuating member for actuating said card impelling means to perform its operating cycle in a predetermined sequence correlated to the operating cycle of said punch operating means, and at least one alignment member carried by said punch carrier and arranged to be actuated during a punch operating cycle to engage an aligning opening of the card before it is punched so as to keep a predetermined column of the card aligned with said punch row during the punching operation.

94. The combination—of a record card formed with a plurality of parallel index columns which are subdivided into a plurality of index positions formed by bridge elements so that a single predetermined bridge element left in a column from which the other bridge elements have been removed represents the information recorded in the column—with a punching machine for selectively punching at least one column of a card so as to record information therein; each of said columns having at least one aligning opening correlated in a predetermined manner to said column for keeping the card aligned during the removal of the bridge elements while making a record in a column; said machine comprising a predetermined number of actuating members, such as keys, a punch carrier, at least one row of elongated punches corresponding to the different actuating members carried by said punch

carrier so as to permit a predetermined movement of a selected punch between a punching position and a non-punching position, a die member having opening portions for cooperation with said punches, card carrier means including a card carrier for holding a record card in a predetermined aligned position between said punch carrier and said die member and card impelling means operative to impel the card carrier to successive aligned positions, punch operating means operative upon actuation of an actuating member to actuate said punch carrier to punch with the punches held in the punching position opening portions in a predetermined aligned column position of a card held by said card carrier, means operative in a predetermined manner in response to the actuation of an actuating member for actuating said card impelling means to perform its operating cycle in a predetermined sequence correlated to the operating cycle of said punch operating means so that the card is impelled from one aligned position to a successive aligned position following a previous card punching operation, and at least one alignment member carried by said punch carrier and arranged to be actuated during a punch operating cycle to engage an aligning opening of the card before it is punched so as to keep a predetermined column of the card aligned with said punch row during the punching operation.

95. The combination—of a record card formed with a plurality of parallel index columns which are subdivided into a plurality of index positions formed by bridge elements so that a single predetermined bridge element left in a column from which the other bridge elements have been removed represents the information recorded in the column—with a punching machine for selectively punching at least one column of a card so as to record information therein; said card having at least one aligning opening correlated in a predetermined manner to said columns for keeping the card aligned during the removal of the bridge elements while making a record in a column; said machine comprising a predetermined number of actuating members, such as keys, a punch carrier, at least one row of elongated punches corresponding to the different actuating members carried by said punch carrier so as to permit a predetermined movement of a selected punch between a punching position and a non-punching position, a die member having opening portions for cooperation with said punches, a card carrier for holding a record card in a predetermined aligned position between said punch carrier and said die member, punch setting means including a punch actuating element operative in response to the actuation of an actuating member to set said row of punches so that the corresponding punch is held in a non-punching position and the other punches in a non-punching position, punch operating means operative in a predetermined relation to the setting of said row of punches for producing a relative motion between said punch carrier and said die member and for punching in a predetermined aligned column position of a card held by said card carrier opening portions facing the punches held in the punching position and leave intact the bridge element of the card facing the punch held in the non-punching position, and at least one alignment member carried by said punch carrier and arranged to be actuated during a punch operating cycle to engage an aligning opening of the card before it is punched so as to keep a predetermined column of the card aligned with said punch row during the punching operation.

96. The combination—of a record card formed with a plurality of parallel index columns which are subdivided into a plurality of index positions formed by bridge elements so that a single predetermined bridge element left in a column from which the other bridge elements have been removed represents the information recorded in the column—with a punching machine for selectively punching at least one column of a card so as to record information therein; each of said columns having at least one aligning opening correlated in a predetermined manner to said column for keeping the card aligned during the removal of the bridge elements while making a record in a column; said machine comprising a predetermined number of actuating members, such as keys, a punch carrier, at least one row of elongated punches corresponding to the different actuating members carried by said punch carrier and arranged to be actuated during a punch operating cycle to engage an aligning opening of the card before it is punched so as to keep a predetermined column of the card aligned with said punch row during the punching operation.

with said punch row during the punching operation.

96. The combination—of a record card formed with a plurality of parallel index columns which are subdivided into a plurality of index positions formed by bridge elements so that a single predetermined bridge element left in a column from which the other bridge elements have been removed represents the information recorded in the column—with a punching machine for selectively punching at least one column of a card so as to record information therein; each of said columns having at least one aligning opening correlated in a predetermined manner to said column for keeping the card aligned during the removal of the bridge elements while making a record in a column; said machine comprising a predetermined number of actuating members, such as keys, a punch carrier, at least one row of elongated punches corresponding to the different actuating members carried by said punch carrier so as to permit a predetermined movement of a selected punch between a punching position and a non-punching position, a die member having opening portions for cooperation with said punches, card carrier means including a card carrier for holding a record card in a predetermined aligned position between said punch carrier and said die member and card impelling means operative to impel the card carrier to successive aligned positions, punch setting means including a punch actuating element operative in response to the actuation of an actuating member to set said row of punches so that the corresponding punch is held in a non-punching position and the other punches in a non-punching position, punch operating means operative upon actuation of an actuating member to actuate said punch carrier to punch with the punches held in the punching position opening portions in a predetermined aligned column position of a card held by said card carrier, means operative in a predetermined manner in response to the actuation of an actuating member for actuating said card impelling means to perform its operating cycle in a predetermined sequence correlated to the operating cycle of said punch operating means, and at least one alignment member carried by said punch carrier and arranged to be actuated during a punch operating cycle to engage an aligning opening of the card before it is punched so as to keep a predetermined column of the card aligned with said punch row during the punching operation.

97. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; a card carrier for holding a record card in a predetermined aligned position between said punch carrier and said die member; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member

5 and punching in a predeterminedly aligned position of a card held by said card carrier opening portions facing the punches held in the punching position, and leave intact a portion of the card facing a punch held in the non-punching position; said cycle means including means operative in response to the actuation of an actuating member to cause them to perform their respective operating cycles in a predetermined correlated sequence so that the punch setting operation is completed before the card is punched; said punch setting means and said punch operating means being so designed, arranged and correlated as to cause their operating elements to be restored to the positions occupied by said elements before starting their operating cycles.

98. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; said cycle means including means operative in response to the actuation of an actuating member to cause them to perform their respective operating cycles in a predetermined correlated sequence so that the punch setting operation is completed before the card is punched and so that the card is brought from one aligned position to a succeeding aligned position between two succeeding punching operations.

99. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a

non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of a card facing a punch held in the non-punching position; said cycle means including means operative in response to the actuation of an actuating member to cause them to perform their respective operating cycles in a predetermined correlated sequence so that the punch setting operation is completed before the card is punched and so that the card is brought from one aligned position to a succeeding aligned position between two succeeding punching operations; said punch setting means, said punch operating means and said card impelling means being so designed, arranged and correlated as to cause their operating elements to be restored to the positions occupied by said elements before starting their operating cycles.

100. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; said cycle means including means operative in response to the actuation of an actuating member to cause them to perform their respective operating cycles in a predetermined correlated sequence so that the punch setting operation is completed before the card is punched and so that the card is brought from one aligned position to a succeeding aligned position between two succeeding punching operations; the elements of said punch operating means and said card carrier means being so designed and correlated as to prevent said punch operating means from being effective if said card carrier is in an out-of-alignment position.

101. In a punching machine for punching holes in a record card; a predetermined number of actuating members, such as keys; a punch carrier; at least one row of elongated punches corresponding to said different actuating members and guided by said punch carrier so as to permit a predetermined movement of a selected

5 punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; said cycle means including means operative in response to the actuation of an actuating member to cause them to perform their respective operating cycles in a predetermined correlated sequence so that the punch setting operation is completed before the card is punched and so that the card is brought from one aligned position to a succeeding aligned position between two succeeding punching operations; said punch setting means, said punch operating means and said card impelling means being so designed, arranged and correlated as to cause their operating elements to be restored to the positions occupied by said elements before starting their operating cycles; the elements of said punch operating means and said card carrier means being so designed and correlated as to prevent said punch operating means from being effective if said card carrier is in an out-of-alignment position.

102. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member, and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; said cycle means including means operative to cause them to perform their respective operating cycles in a predetermined correlated sequence so that the punch setting operation and

card impelling operation are completed before the card is punched.

103. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; a card carrier for holding a record card in a predetermined aligned position between said punch carrier and said die member; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; at least one of said cycle means being associated with power means including a normally ineffective coupling connection operative to supply operating power to said cycle means when said coupling connection is rendered effective; said cycle means including means actuated in response to the actuation of an actuating member for rendering effective said coupling connection and operative to cause said cycle means to perform their operating cycles in a predetermined correlated sequence so that the punch setting operation is completed before the card is punched.

104. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; a card carrier for holding a record card in a predetermined aligned position between said punch carrier and said die member; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; at least one of said cycle means being associated with power means including a normally ineffective electric control circuit operative to supply operating power to said cycle means when said control circuit is rendered effective; said cycle means including means actuated in response to the actuation of an actuating member for rendering effective said control circuit and

operative to cause said cycle means to perform their operating cycles in a predetermined correlated sequence so that the punch setting operation is completed before the card is punched.

105. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; a card carrier for holding a record card in a predetermined aligned position between said punch carrier and said die member; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; at least one of said cycle means being associated with power means including a normally ineffective coupling connection and a normally ineffective electric control circuit operative to supply operating power to said cycle means when said coupling connection is rendered effective and when said control circuit is rendered effective; said cycle means including means actuated in response to the actuation of an actuating member for rendering effective said coupling connection and said control circuit and operative to cause said cycle means to perform their operating cycles in a predetermined correlated sequence so that the punch setting operation is completed before the card is punched.

106. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; at least one of said cycle means be-

ing associated with power means including a normally ineffective coupling connection operative to supply operating power to said cycle means when said coupling connection is rendered effective; said cycle means including means actuated in response to the actuation of an actuating member for rendering effective said coupling connection and operative to cause said cycle means to perform their operating cycles in a predetermined correlated sequence so that the punch setting operation is completed before the card is punched, and so that the card is brought from one aligned position to a succeeding aligned position between two succeeding punching operations.

107. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; at least one of said cycle means being associated with power means including a normally ineffective electric control circuit operative to supply operating power to said cycle means when said control circuit is rendered effective; said cycle means including means actuated in response to the actuation of an actuating member for rendering effective said control circuit and operative to cause said cycle means to perform their operating cycles in a predetermined correlated sequence so that the punch setting operation is completed before the card is punched, and so that the card is brought from one aligned position to a succeeding aligned position between two succeeding punching operations.

108. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned posi-

tion to a succeeding aligned position; punch setting cycle means including a punch displacing element operative in responsive to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; at least one of said cycle means being associated with power means including a normally ineffective coupling connection and a normally ineffective electric control circuit operative to supply operating power to said cycle means when said coupling connection is rendered effective and when said control circuit is rendered effective; said cycle means including means actuated in response to the actuation of an actuating member for rendering effective said coupling connection and said control circuit and operative to cause said cycle means to perform their operating cycles in a predetermined correlated sequence so that the punch setting operation is completed before the card is punched, and so that the card is brought from one aligned position to a succeeding aligned position between two succeeding punching operations.

109. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; at least two of said cycle means being associated with power means including a normally ineffective coupling connection operative to supply operating power to said cycle means when said coupling connection is rendered effective; said cycle means including means actuated in response to the actuation of an actuating member for rendering effective said coupling connection and operative to cause said cycle means to perform their operating cycles in a predetermined correlated sequence so that the punch setting operation is completed before the card is punched and so that the card is brought

from one aligned position to a succeeding aligned position between two successive punching operations.

110. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; at least two of said cycle means being associated with power means including a normally ineffective electric control circuit operative to supply operating power to said cycle means when said control circuit is rendered effective; said cycle means including means actuated in response to the actuation of an actuating member for rendering effective said control circuit and operative to cause said cycle means to perform their operating cycles in a predetermined correlated sequence so that the punch setting operation is completed before the card is punched and so that the card is brought from one aligned position to a succeeding aligned position between two successive punching operations.

111. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in

the punching position, and leave intact a portion of the card facing a punch held in the non-punching position; at least two of said cycle means being associated with power means including a normally ineffective coupling connection and a normally ineffective electric control circuit operative to supply operating power to said cycle means when said coupling connection is rendered effective and when said control circuit is rendered effective; said cycle means including means actuated in response to the actuation of an actuating member for rendering effective said coupling connection and said control circuit and operative to cause said cycle means to perform their operating cycles in a predetermined correlated sequence so that the punch setting operation is completed before the card is punched and so that the card is brought from one aligned position to a succeeding aligned position between two successive punching operations.

112. In a punching machine for punching holes in a record card; a predetermined number of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of the card facing a punch held in the non-punching position; at least one of said cycle means being associated with power means including a normally ineffective coupling connection and a normally ineffective electric control circuit operative to supply operating power to said cycle means when said coupling connection is rendered effective and when said control circuit is rendered effective; said cycle means including means actuated in response to the actuation of an actuating member for rendering effective said coupling connection and said control circuit and operative to cause said cycle means to perform their operating cycles in a predetermined correlated sequence so that the punch setting operation is completed before the card is punched, and so that the card is brought from one aligned position to a succeeding aligned position between two successive punching operations; said control circuit having an element actuated by the operation of said coupling means for rendering said control circuit effective during an operating cycle of said cycle means.

113. In a punching machine for punching holes in a record card; a predetermined number

of actuating members, such as keys; a punch carrier; at least one row of elongated punches corresponding to said different actuating members and guided by said punch carrier so as to permit a predetermined movement of a selected punch between a punching position and a non-punching position; a die member having opening portions for cooperation with said punches; card carrier means including a card carrier for holding a record card in a predetermined aligned position between said punch carrier and said die member and card impelling cycle means operative to impel said card from one aligned position to a succeeding aligned position; punch setting cycle means including a punch displacing element operative in response to the actuation of an actuating member to set said row of punches so that the corresponding punch is held in a non-punching position and the other punches are held in punching positions; and punch operating cycle means operative for producing a relative motion between said punch carrier and said die member and punching in a predeterminedly aligned position of a card held by said card carrier opening portions facing the punches held in the punching position, and leave intact a portion of card

5 facing a punch held in the non-punching position; at least two of said cycle means being associated with power means including a normally ineffective coupling connection and a normally ineffective electric control circuit operative to supply operating power to said cycle means when said coupling connection is rendered effective and when said control circuit is rendered effective; said cycle means including means actuated in response to the actuation of an actuating member for rendering effective said coupling connection and said control circuit and operative to cause said cycle means to perform their operating cycles in a predetermined correlated sequence so that the punch setting operation is completed before the card is punched and so that the card is brought from one aligned position to a succeeding aligned position between two succeeding punching operations; said control circuit having an element actuated by the operation of said coupling means for rendering said control circuit effective during an operating cycle of said cycle means.
